Application February 5, 1930, Serial No. 425,966

33 Claims. (Cl. 235—61.7)

This invention relates generally to machines of the type wherein a punched card controls the setting of the items, and more particularly to that class adapted to totalize a series of items, 5 and employing printing devices for obtaining printed records of totals and items. Many novel control devices useful in machines of different classes are disclosed in this specification.

More specifically, it is a primary object of the 10 present invention to provide an accounting machine which will be simple and inexpensive to manufacture. The machine has an increased capacity while using a standard size punched record card, and also has novel printing devices to accommodate the increased amount of data to be 15 printed. A totalizer of novel form and compact construction, which accumulates items as they are entered into the machine, is provided and is adapted to control the printing devices in printing totals. A novel comprehensive form of non- 20 adding and non-printing control is provided by means of which the magnitude of the data in the alphabetic, numerical or date scales determines whether the data will or will not be added, 25 printed or totalled.

One phase of the invention has for an object the provision of improved devices for sensing combinational hole records and transposing the result of such sensing into differential linear 30 positions of adding and printing actuators in the machine. In the disclosed form of jacquard mechanism, the combinations of only four punched holes in a record card control the positioning of an actuator into one of sixteen positions. Also, the combinations of five holes control the positioning of an actuator into one of 35 thirty-two positions. A novel use of differential gearing is disclosed in the jacquard mechanism, and the method of construction disclosed may be expanded to be employed where any number of 40 record holes are sensed in combination. The maximum number of combinations of the record holes are used to determine different actuator positions. The jacquard structure is novelly constructed so that it is of such shape and thickness that a plurality of such structures may be operated in the same plane and may cooperate with a single column of record holes in a record card. 45 By means of the differential gearing construction used in the disclosed jacquard devices, a plurality of members operated under control of the card sensing mechanism are adapted to contribute simultaneously to the movement of an 50 actuator. Thus, the time of operation is much

shorter than if each member separately effected a partial movement of the actuator.

It is an important object of the present invention to construct the totalizers so that a large 5 number of them will occupy but a small amount of space. The few parts in the novel totalizer have been so arranged that each order or bank of the totalizer will require but one thickness of metal. In the past, a plurality of parts arranged in different planes were necessary to the proper 10 functioning of a transfer mechanism. Herein is disclosed a totalizer structure requiring only the absolute minimum of space per bank, namely; a space equal to the thickness of one part. Therefore, it is possible, by utilizing the principles of 15 construction herein disclosed, to confine a 20 bank totalizer in a space one inch in width, one inch in thickness, and about two inches in height (this is only an illustrative example).

The transfer mechanism embodied in this 20 machine is of the nines coupling type, so that transfers are effected simultaneously in all of the orders of the totalizer that are set to receive a transfer.

A feature of the invention is the use of a large 25 tooth on the totalizer wheel as a coupling means when the wheel stands at the nines position.

Another feature is the utilization of the movement of the pinions out of mesh with the actuators as a means of rotating the pinions which are 30 due to receive a transfer.

The above features, together with a simple bail for the transfer mechanism, all contribute to the novel construction shown of a simple form of totalizer composed of a few inexpensive stamped 35 parts easily manufactured and assembled.

A totalizer engaging mechanism of a novel and simplified form is employed in the present machine and is so constructed that a control section of the machine will be adapted to easily 40 alter the accumulating functioning of the machine during operation, as a control is exercised.

Another object is to provide a totalizer selection device which is adapted to select by operation of the machine at one time and by manual 45 setting at another time. During regular adding operations this selection device selects two totalizers, one special and one common. However, when a total is to be taken, and the selector is manually set, it is only possible to select one 50 totalizer for each operation of the machine.

It is also an object of the present invention to provide printing devices which are able to print more data simultaneously in a limited space than was before possible in machines of the tabulating 55

or accounting class. The mechanism disclosed is adapted to print from one record card in one operation the same amount of data that before required three record cards and three operations of a machine. By means of the present printing device a name, address, amount, etc., can now be printed in one operation and in the proper position on the record media. A feature of the printing devices is that an address may be printed directly under a name, in the standard mailing form, during a single operation of the machine. The position of the name and address on the record paper (it may be a bill, receipt, statement, etc.) is important, especially when used in the mails with a window envelope. To secure the novel results described above, related type bars are arranged alternately between other type bars, and they are impressed against a platen by eccentrics. The use of these operating eccentrics results in a simple noiseless type of printing that does not require printing hammers and the space usually required for such devices. An additional feature of the printing devices is that they are constructed to print a duplicate record of all matter printed.

A more complete control of the functioning of an accounting machine is also an object of this invention. Heretofore, when a control of the functioning of a machine, such as no-print, no-add, total, etc., was set, that control would prevail and would not be varied no matter what data were printed, added or totalled. The present machine provides control for many of the functions of the machine that is so devised that when the data presented by the record card do not satisfy predetermined requirements, which are decided upon and set up on the machine before its operation, the said controls will separate such data from the other data that do satisfy the requirements. Because of its complexity, this object will have to be explained in detail.

In this specification it is assumed that the date scale starts at January and progresses along to December so that July would be higher than June in the scale. In the alphabetic scale, *a* may be taken as the first letter and all other letters in order up to *z* may be mentioned hereinafter as being higher in the alphabetic scale.

An object is to so make the control that not only can one denomination of a number, or period of a date, or letter of a name, be the determining factor of control of printing, accumulating, total-taking and sorting; but, that a full number, date or name, may be the determining factor. The highest order of the number, etc., set up will not be the only order capable of manifesting that the data presented by the card are of a lower or higher place on the scale used, but every order of the setup has this power. If, for instance, 76, 82 be set up for a control and 76, 92 be presented by the card, then the dimes order control will have the ability of manifesting that the number tendered is larger; if 77, 62 be presented, then the dollars order control will have this power of discrimination. The same is true of the controls in the date and alphabetic scales. When a number is set up to control, a plurality of denominational order elements in the control device are so coupled, that control will not be exercised by dimes, dollars or cents alone, although that is possible, but a full number consisting of the units, tens, hundreds, etc., denominations may be set up on the controls and then said control will be affected by the full number of units, tens, etc., denominations presented by the punched card. In a like

manner, when a date is considered, not alone can a certain year, month or day be made the controlling factor, but the full date of all three periods combined may control at the same time. A control of a date consisting of a certain year, month and date may be set and will simultaneously act as a unit in controlling according to the place in the date scale of a date on the punched card of a certain year, month, and day, which also acts as a unit. During operation under name control in the present machine, the first letter or any letter of a name is not alone the sole determining factor of control, although it may be so used. In a novel fashion all the letters or a few of the letters of a name may at the same time be controlling factors in selective control, according to the place a name of a man, city, state, etc., presented on a punched card occupies in the alphabetic scale. For example, the letters OMTIN may be decided upon as the control wished exercised over certain names about to be presented in the machine by punched cards. As the cards run through the machine, and the control mechanism functions, not only will names such as Prota or Winte, which are higher in the alphabetic scale than the first letter, influence the controls to make manifest that these names are higher in the alphabetic scale, but names such as Omtip or Omwal will have the same influence, even though the change in the alphabetic magnitude occurs in the center or at the end of a name. To exercise this novel control, the devices are arranged so that the setting of manipulative elements to a certain place in the numerical, date, or alphabetic scales, plus the setting of an element to indicate whether control is desired above, below, or exactly at that certain place in the scale used, will, upon operation of the machine control devices, vary the regular printing, paper feeding, accumulating, total taking, and sorting of the data within the control of the two elements, from the data outside of the control of the range predetermined by the two elements.

The above mentioned manipulative elements are so situated and constructed that when they are set in a particular position above a related type bar or actuator, the movement of the actuator to an extent corresponding to the particular position held by the manipulative element, presents a notch in the actuator and allows a controlling movement of the manipulative element to take place. On each side of the notch, the actuator is cut to present a different level to the said element, thus affording an indication whether the actuator has moved more or less than the number set up.

The requirements which the operator of the machine may desire, are made ready to exercise control by first setting up a certain amount, number, agent, age, policy number, date, operator, occupation, name or address, by the manipulative knobs provided for the purpose; then next he can require, by moving a lever, that the above data will control in one of five different ways. The first position "Print" of the lever denotes that the machine is to function in its usual fashion, which means it will print and add any data presented by the punched cards. The second position of the lever is the "above index" position. With the lever in this position, the machine will print, add and sort only the data which include a name, number or date which is higher in the numerical, dating or alphabetic scales than that name, number or date set up by the manipulative knobs. Thus, if \$15.00 is set up by the

knobs and a punched card presents data including the amount, \$15.00, or under, the data will not be printed, added or sorted. However, if the data included an amount \$15.01 or over, the data would be printed, accumulated and sorted. In a like manner, if Dec. 29, 21 is set up by the knobs, and data are presented dated Dec. 29, 21 or before, the data will not be printed, added or sorted, but if the data are dated Dec. 30, 21 or later, printing, adding and sorting will take place in the usual manner. If EN is set up by the name knobs and data are presented including a name such as ELRIGHT or EMSILL or a name lower in the alphabetic scale; the data will not be printed, added or sorted. However, if the data include a name such as EODISE or EPSTEIN or a name higher in the alphabetic scale, then printing, adding and sorting will occur. Any other datum such as policy number, kind of occupation, address, etc., may be used to control in a similar fashion. By progressive setups of the name knobs, an alphabetical listing and sorting of a group of cards is possible. The third position of the lever is the "exact" position. With the lever in this position the machine will print, add, and sort only the data which include a name, number, or date which is exactly the same as that requirement which is set up on the manipulative knobs by the operator of the machine. The fourth position of the lever is the "below index" position. Under this control the machine will print, add and sort only the data including a name, number, or date which is smaller or lower in its scale than that set up on the adjustably set knobs. With this control, the action of the lever in the "above index" position is reversed. Taking the same examples of the setting of the manipulative knobs given above, then given data presenting \$14.99 or under, a date of Dec. 28, 21 or earlier, a name 40 of EMSILL or lower in the alphabetic scale, such data will be printed, added, and sorted, and any data higher in the respective scales will be rejected. The fifth position of the lever is the "no print" position. In this position a control is affected so that printing will not occur, regardless of the nature of the data on the card or the setup of the adjustable knobs. Accumulating will take place in the normal fashion at this time, unless an accumulator control key about to be 45 described is depressed.

The above general discussion gives an outline of the control exercised by the manipulative control lever and adjustable knobs during the normal operation of the machine. Aside from the above, however, other special controls are provided for use during total taking operations to vary the control in accordance with conditions existing at such times. These novel features will next be described as additional objects of this invention. The machine includes many novel methods of totalizer engaging during total taking. An accumulator control key is part of this mechanism. During regular adding operations, this key determines whether adding will always take place, or whether the adding will take place under control of the control section described above. When under such control, data not printed will also not be added. During total taking, however, depression of this key will result in novel control of the totalizer meshing with the actuator. The usual total, sub-total, and non-add keys are provided, and they will normally cause the machine to time the totalizer engagement with actuators in the usual fashion as is their action in most accounting machines. Under such normal condi-

tions the total key will, when depressed, cause clearing of the totalizer and printing of the amount standing thereon. The sub-total key will cause printing of the amount standing on a totalizer, at the same time retaining the amount in the totalizer. The non-add key will, as its name implies, prevent adding. Now, however, depression of the accumulator control key in addition to one of the above mentioned keys will cause functioning not heretofore possible in any accounting machine and of decided utility in many uses of such machines. Depression of both the total and control keys will result in a control of total taking by the amount standing on the totalizer. The control lever will be put in one of its five positions, and the adjustable knobs mentioned above will be set to a particular amount. Then, upon operation of the machine, any amount not meeting the requirements set by the controls will change the totalizer meshing so that the amount taken out by the restoring of the totalizer to zero will again be put in the totalizer, thus changing the total taking function to sub-total taking. Therefore, the amount that does not satisfy requirements, or that for some other reason is wished retained, will be kept in the totalizer for all future operations, such as additional adding upon, or reference to, in checking up delinquents in payment, or accounts overdrawn, etc. It is apparent that the retaining of certain data in the totalizers at times, even though they are set for zeroing, is a useful method of operating the machine. With this type of use of the machine it would be well to arrange the printing on the detail strip so that it will always occur. This can be done by an alternative way of construction as suggested above in connection with printing.

If the sub-total and accumulator control keys are both depressed there will result a control adapted to change the sub-total function according to the amount standing on the totalizer. With the controls set and the machine operated, movement of the actuators to an amount satisfying the requirements set by the controls will change the totalizer meshing so that the amount rolled out of the totalizer wheels as they are brought to zero will not be rolled back in again, thus the sub-totalizing function will be changed to zeroized total taking. In this way any amount that satisfies set requirements, or for some other reason such as closing an account that is paid up, or clearing after a last installment is paid, is cleared out of the totalizer.

The usefulness of clearing out a totalizer, when set for a sub-total is believed apparent. The adaptation of the machine to choose either a total or sub-total function, depending upon the amount in the totalizer, is believed novel and of decided utility. It is also contemplated that additional wheels could be put on the totalizer so that all the data now presented by the punched card could be held in a totalizer and represented by positioned wheels. With this done, the total taking function could be varied and controlled, not only by the amount standing on a totalizer, but also by the date, name or some other designation presented by the totalizer when a total is being taken therefrom.

If the non-add and accumulator control keys are both depressed at the same time no change in function will take place, the totalizers will be held out of mesh with the actuators throughout the entire stroke.

Another method of control has been devised and is thought admirably fitted for use in the

present machine. It departs only slightly from the construction of the controls mentioned above, but effects an altogether different mode of control. The controls described in outline above, control when data is below, above or exactly at a certain point in alphabetic, dating or numerical scales. This other control would be exercised between two points in a scale. One example is control between two dates such as between December and April, representing a quarter year in which it is often convenient to have the data falling within that period tabulated and accumulated and assorted aside from all other data. Another example is that of amounts or numbers. At times it is well to isolate data having numbers say between 500 and 800, or having amounts between \$60.00 and \$90.00, from other data outside this range of numbers. So also in alphabetic control it may be well at times to separate data including 'names beginning with K, L and M from all other data.

It is an object that this control between two points should exercise all the same controls that have been explained above in connection with the control that was exerted on data below, above and on a certain index. Such controls include accumulating, printing, paper feed, sorting, etc., during normal operations, while during total taking, the functions of zeroizing and sub-total taking may be changed under influence of the control.

An important object is to secure a sorting or selecting device that will separate out of a mass of data a certain group of data, not alone of one characteristic, but of a group of characteristics between variable limits set by the machine. Heretofore, selection depended upon a single characteristic of the data and only by later combining the results of single selection was group selection secured.

It is a further object of this invention to provide a sorting device that is incorporated in the tabulating and accumulating machine. Thus, the usual extra sorting machine is dispensed with. Sorting of the punched cards is accomplished in the present machine simultaneously with printing and accumulating operation. Thus, the extra time usually required for sorting is saved by the present device. The sorting is done under the influence of the novel control described generally in these objects and more specifically further along in the specification.

While the above outline of objects presents the general purpose of the present invention, many other worthy and novel purposes will be apparent as this specification continues.

The illustrative machine

To aid in describing this invention, it has been thought advisable to apply it to a specific case. A certain class of machine has been illustrated in the drawings, a general outline of which machine will be given now so as to help the understanding of the detail description given herein-after. Even though this machine serves admirably to illustrate the important features of the invention it is to be understood that the specific application of these features is not intended to restrict their use but that many variations and adaptations of the machine for use in other fields of business are contemplated.

A class of business has been chosen that it is thought will best illustrate the practical use of the novel features of the invention. The machine illustrated is adapted for use by a large insurance company. It is thought that such a concern may have different districts each having

a group of agents who solicit the disposal of the various policies of the company to the public. Each district would have a machine such as that disclosed and also have a punch card system co-operating with the machine. This punched card system would require a keypunch machine and operator for transferring the incoming data from the policies, etc., onto the punched cards. These cards would then be filed in accordance with a certain system. It will be assumed here that they are filed according to the kind of policy, each group of cards say of the same color, being of the same type of a policy. These policies may demand different terms of payment, some annually, some quarterly, some monthly. The present machine is adapted to print bills ready to send out or statements calling for such payments.

The data recorded on the punched card are intended to cover most statistical requirements. There is plenty of room left on the card, after the following data are on, for other records. It will include the following:

The policy holder is given a number that will completely distinguish him from any other having the same name, etc. This number will also be a convenient means of sorting a particular record card out of a group of other record cards. A region punched to represent an amount is also on the card. This amount is the premium of the policy and requires payment at intervals to keep the policy in force. If the amounts increase or decrease, a slight change in the layout of this machine would provide different spaces, one for each amount, which could be progressively printed as the policy matures. The age of the policy holder at the date of the taking out of the policy is recorded on the card mainly for statistical use. The agents are assigned numbers and these numbers are also recorded on the record card. The agent who is responsible for the taking of the policy is recorded by having a punching corresponding to his number inserted in a section reserved for it on the punched card. The occupation of the policy holder is given one of a number of code numbers, and punching corresponding to this number is cut in an appropriate portion of the record card. This also is an item mainly for statistical use. The code number of the key punch operator who transfers the data to the record card will also be represented by a combination of holes in the card. This designation is provided merely for placing the responsibility for mistakes made in making the record cards. The date of the issue of the policy is also represented by a combination of holes on the card. This portion of the record is useful in governing the time of sending annular or periodical statements and for statistical purposes also. The kind of policy is also represented on the card and may be used in sorting aside from the color differentiation. The full name and address of the policy holder are also presented by code punchings on the card. These punchings provide the means of addressing the statements, besides furnishing means whereby an alphabetic listing of records according to name may be made, or a listing according to location in a certain city or state is possible. The convenience of having all these data on one card instead of on three or more cards is believed apparent. Thus, it is seen that a complete record of all information concerning a policy is contained in a single record card.

Full printing facilities are incorporated in the machine for recording all the data mentioned above, as they are required. The group of

5 punched cards upon which operation is desired is placed into a feeding rack on the machine. From this rack they are fed down into cooperation with a jacquard device which utilizes all combinations of holes on the card to move type bars or actuators to an extent necessary to place a pair of type on the bar, corresponding to said combination, opposite the platens. Printing may then be performed on two record sheets. The one

10 sheet is of the form of a bill, and it is cut off a supply roll and issued out of the machine after printing. This sheet is suited for mailing and may be sent out in a windowed envelope to the policy holder reminding him of a payment due.

15 The other sheet is of the form of a record strip and it is kept in the machine, being wound on a storage roll after each printing operation. This strip is well suited for bookkeeping or statistical department use and may be removed from the

20 machine for such use at any period, most likely at the end of every day. Means for no-printing, total printing, and other controls will be explained hereinafter.

25 There is a group of totalizers provided in the machine. The group comprises a separate totalizer for each of fifteen agents; and a grand totalizer. During regular item entering operations, the correct agent's totalizer is automatically selected by a train of connections controlled by the
30 movement of the agent typebar under control of the related combination of holes on the card. At the same time the grand totalizer is meshed simultaneously with any one of the agents' totalizers. These totalizers are operated by rack teeth
35 cut in the amount typebars which are also under control of a section of the punched card. Thus, it is clear that during regular operations the totalizer operation and selection is wholly automatic and under control of the punched card.
40 However, during total taking other conditions are prevalent. Only one totalizer at a time is engaged, and besides at that time it is contemplated that a blank card will be in the jacquard device so that no selections will be made by automatic means. A selection lever is provided for this purpose, and movement of it to one of several notch positions out of normal, will select one of the fifteen agent totalizers or the grand totalizer for total taking.

50 During the regular operation, as the cards pass through the machine, an agent's totalizer will have accumulated on it the amounts standing on every card which contains the combination of holes denoting that that particular agent wrote out the policy. Thus, as the bills are issued for the policies for which a certain agent was responsible, there will be accumulated in the related totalizer the amount of those bills. At the same time, since the grand totalizer is always accumulating during regular operations, it will have accumulated in it the total of the amounts standing on all agents' totalizers. Of course, this will also be the sum total of the amount of all the bills sent out.

65 Number, totalizer, sub-totalizer, and non-add keys are provided to condition the mechanism meshing the totalizer with the actuators so that a total, sub-total, or non-add operation of any of the totalizers can be secured. Upon depression of
70 the total key, movement of the selection lever to one of sixteen positions, and subsequent operation of the machine, the total of the selected totalizer will be printed and the totalizer will be cleared. Movement of the selection lever will also place a
75 designation type in position to print upon the rec-

ord material, adjacent the item, the agent's number and a total sign showing that a total has been taken. At the time of taking a total a blank card appears in the jacquard frame to prevent actuation of all the feeler pins and movement of all unnecessary type bars. In almost an identical manner, operation of the machine in combination with the sub-totalizer key will produce a printed total of the amount standing on a certain totalizer, leaving the amount remain in the totalizer at this time, however. The non-add key is suited for use during regular operations of the machine. At such times as this key is depressed, printing may take place but accumulation of the amounts in the totalizer will be prevented. One use of this feature would be when follow up or duplicate bills are needed; but the amount does not want to be added at this time for then it would be presented twice in the totalizer. 5 10 15

The uses to which the totalizers could be put are many. As described in connection with use in registering the amounts of an agent, they could be used to find out the commission due the agent for his efforts in placing the policies. The amount on the totalizer, of course, is the amount billed the various policy holders solicited by the agent, and his commission will only be a percentage of it. As these commissions may diminish in percentage as the policy ages, only the policies secured by him over a certain period, usually say a year, may be selected at one time. These cards as they are selected (by devices about to be described) from others of their group (printing bills and a record meanwhile) will accumulate the amount over the certain period. This amount may be printed, and in crediting the agent, it will later be multiplied by the percentage of commission that the period calls for. So also, in a like manner, cards of another period may be selected and accumulated and later totalled from the agent's totalizer. This process may continue until the records are up-to-date. This may be done to determine the commission of fifteen agents simultaneously, and meanwhile the grand totalizer will record the sum amounts upon which the commissions for all agents are based. The agent's commission may also vary with the kind of policy. This condition could be taken care of exactly as above, but selection of accumulation would depend on "kind of policy" rather than on date. When the commission is affected by two of the characteristics of a policy, there can be two selections by two operations of the machine. The first operation will be a non-add and will merely select required cards according to one characteristic. The next operation will select and add according to the other characteristic.

The above example of letting the totalizer represent an agent was chosen for its simplicity. There are many other uses to which the totalizers may be put in the machine perhaps to better advantage. But it is believed that the essence of the invention is fairly well illustrated when used as described. The totalizers may represent a kind of policy, a certain period of time, or even the policy holder. Many novel conditions would be brought about if the machine were provided with a large number of totalizers, each one representing a policy holder and being selected by his number. Then the amount accumulated on a totalizer would represent the amount paid on a policy, providing that all the bills issued by the machine were paid. If they were not paid, any follow-up system as now used would detect delinquents. Dividends, etc., could be figured from that

amount. Delinquents in payment could also be detected from shortages in these amounts.

The machine could also be enlarged so that a set of totalizers may be provided for each characteristic of the data on the cards. With this construction an amount could be accumulated simultaneously in the totalizer for an agent, kind of policy, date, policy holder, etc. The construction of a totalizer occupying small space greatly 10 enlarges the feasibility of such a multiple totalizer machine keeping within a reasonable size.

At the front of the machine is located a control section. It consists of a control lever on one side, and a control plate extending across the machine 15 and having a plurality of notched slots in which knurled knobs may be shifted. The control lever is shiftable in a notched slot to one of five controlling positions. Each position determines in what way the control knobs are to effect control 20 of the machine. Each control knob cooperates with a related type bar or actuator, and has as many controlling positions as the type bar has printing positions, for example, the months control knob has 12 controlling positions. These 25 control knobs are arranged in groups, each group being a separate characteristic of the data handled by the machine. For example, there are 5 amount control knobs, 3 date control knobs (year, month, day), 2 policy holders name control knobs, 30 etc. It is contemplated that usually only one group of knobs would be used for controlling at a time, although there is no reason why two or more groups should not be used as a simultaneous control. To aid in placing the control knobs in position, the slots in the control plate are notched 35 and on the side of each notch are indicia identifying the position. So that once a certain number, name, or date is decided upon as a desired control, all that is necessary is to lift the related 40 group of control knobs out of their inoperative position at the front of the control plate and move them to, and place them in, the notches corresponding to the number, name, or date selected. The knobs will remain in this position until moved 45 by the machine operator for other control. In this position they are adapted to change the functioning of the machine in many ways, the one way in which they are to control at one time being determined by the control lever already 50 mentioned. This control lever in one position (print) disables the controlling action of the knobs so that printing, accumulating, etc., will occur no matter what position the control knobs 55 occupies. In the next position "above index" of the lever suppressive control is exerted on data whose magnitude in their respective scales is below that magnitude to which the control knobs have been set. For example, if the amount control knobs are set to \$3.69, and a card with an 60 amount of \$3.75 is tendered to the machine, such data will be acceptable, and printing, accumulating, sorting, etc., will occur in the normal manner. If the amount had been \$3.65, however, the controls would have functioned to disable the 65 printing, accumulating, etc., of the data. In the same manner any other group of controls, say in the name or date scales, would have exerted their control on any data presented that were lower in their scale. The "exact index" position 70 of the lever is one of decided utility. When the lever is in this position and the control knobs of a group are placed to represent an amount, name, date, etc., only the data including that certain amount, name, or date will be printed, accumulated, etc. All other data will not be printed,

accumulated, etc. For example, if Jan. 10, 1920, is set on the date control knobs, only data including that date will be printed, accumulated, etc. In the next position "below index" of the lever, the conditions described above in relation 5 to the "above index" position are just reversed. For example, if SM be set on the name control knobs at this time, data including a name such as Sloss will be printed, etc., but if a name such as Snover is presented, the data associated therewith will not be printed, etc. The next position "no print" of the lever, controls for preventing 10 printing, accumulating, etc., no matter what data are presented by the punched cards or what position the control knobs assume. Another position "between index", a control mechanism for which 15 is shown in the drawings, could be added on the lever or the "above index" position could be used. It would control between two points set by two control knobs in a slot of any scale. For example, two knobs in the date scale could be set at 20 Mar. and July, then operation of the machine would print, accumulate, etc., only those data of a date between Mar. and July. All others would be rejected.

These various controls above mentioned are very useful for statistical work in a large insurance business. A few of the examples of how the machine may be employed in such a business will now be given. The amount control knobs may be 30 set to a certain amount and then with the control levers in "exact index" position only the data relating to policies having that certain premium will be listed, sorted, and accumulated, out of all others. The record furnished by using this 35 control, and setting up different amounts until all cards are recorded, would show which is the popular premium, which is second in demand, etc. Or, with the lever in "above index" position and the amount control knobs set to a certain amount, 40 only the records of policies having premiums larger than that certain amount will be printed, etc. All others will be merely fed through the machine. So also with "below index" control, 45 only policies of smaller premiums than the set up will be recorded. And with a "between index" control, only policies having premiums ranging between the amounts set up will be recorded.

With the age control knobs set to a certain age, and the control lever in "exact index" position, only those policies having, in the data on them, that certain age will be printed, accumulated and sorted. All others will be discarded. If this control is used in conjunction with the date control, the statistics can always be kept 50 up to date as regards the age of policy holders, the age on the record card being that of the policy holder when taking out the policy. The method to use would be, first; sort the cards according to date, giving a batch of cards for each year, 55 say 1916, 1917, 1918, etc. Then if the present date is 1920 and the 1917 batch of cards is being tabulated under an age control of 25, the real age 60 of the people holding those 1917 policies is 28 years, and this fact could be considered in compiling the statistics. With the "above index" or "below index" control being exercised, only policies are recorded in which their holders are above or below, respectively, the age set up by knobs. This control would be well employed in finding 65 how many policies are outstanding to people in a dangerous age to insure, say above 85 years and below 9 years. The "between index" control would effect such a control also, if the age control knobs are set to include a certain range of ages. 70 75

say between 5 and 9 years. All policies allotted to children of that age would be recorded, and all other policies would not be recorded.

If the agent's control knob be set in a certain position and the machine operated under "exact index" control, only the policies secured by the certain agent will be recorded. If either the "above index", "below index" or "between index" be used, only policies secured by agents in the group respectively above, below, or between the setup will be recorded. This control will be especially useful if the agents are divided into groups for competitive purposes, one group being pitted against another in soliciting business.

15 The number assigned to each policy holder and represented on the punched card may also be made useful in conjunction with the control mechanism. The data on the cards may be selected according to such a number or group of 20 numbers. One form of the policies is numbered in the order of issuance. Then, in conjunction with the date selection there can be found and tabulated the number of policies issued between certain dates; or in another case requiring the 25 data of a certain group of policies between two policy numbers, after setting of the number control knobs, operation of the machine will record this information.

If the cards upon which mistakes have been 30 made in transferring the data from the policy to the card are separated out of the main bunch of cards, means is provided for fixing the responsibility for such errors. A section on the card is allotted to record the key punch operator's number. The control section is provided with an operator control knob and means of selecting the cards of one or a group of operators for tabulation. So that out of the bunch of cards, the ones made by a certain operator may be 40 selected and recorded, or the cards made by a certain group of operators may be separately recorded.

An occupation control knob is provided on the control plate, and the punched cards are adapted 45 to contain a combination of punched holes representing the policy holder's occupation. By means of these provisions, the data on some of the cards, because of having common occupational requirements, may be selected out of the 50 other data presented to the machine. Also, a group of occupations representing a common class of labor may be the determining factor in the selection of data.

The date control may be exercised to secure 55 useful operation on the machine. By this means the expired policies may be selected from the others. Periodical payments of the premiums may be insured by the control of the dating data over the issuance of the bills. The annual paying 60 policies could be selected according to the month of their issue. Say a policy was taken out on May 14, 1916, then a bill should be issued May 1, 1917, May 1, 1918, etc. That could be done in this machine by setting the date control knobs to 65 control between May and June. Then, all policies whose date falls in that category will be selected and tabulated and have bills printed. In a like manner, policies payable quarterly would be picked from a group four times a year. Say 70 the quarterly policy is dated June 10, 1917, then on the date of Sept. 1, 1917, Dec. 1, 1917, and Mar. 1, 1918, etc., the date control knob will be placed at June position, and the data on all the June policies will be printed on a bill and a record 75 strip, the amounts will be accumulated in total-

izers and grand totalizers, and the cards will be sorted. To sort out expired policies, the control lever is set to "below index" and the date (20 or 30 years prior to the present date, according to kind of policy) is set up on the date control knobs. 5 Then, out of the cards run through the machine, those below the set date, in other words expired, will be tabulated, accumulated, and sorted from the rest. As shown, one control bank is provided for the year designation, giving control extending over 32 years. However, two banks may be assigned to this designation if a longer range of time control is desired.

The "Kind of Policy" control may be utilized to sort the cards for placement in their proper 15 office files. Two banks of controls are provided for this characteristic so that more than 900 different kinds of policies could be selectively controlled.

The "Name" control is one that may have a 20 multitude of uses. Only two banks of controls are shown devoted to this designation, as the first two letters of a name will generally place it, in a group of names that is not too large. Where a large number of names are handled, 25 and many names differ only in the third or fourth letter, then additional controls should be provided as in the "City" controls. In the present machine, by setting the control lever to "exact" 30 position and the name control knobs to AB, AC, AD, etc., successively, and running a series of cards through between each set up, an alphabetic listing of the names may be made, plus a record of the data on the selected cards. In the same manner a card containing a particular name 35 may be picked out of a series of cards.

An address of a policy holder may determine 40 selective control. The record card has provisions for street and street number printing, also space for city and state designation. The control section has "City" and "State" control knobs so that selection may be determined by geographical location of policy holders. With the "City" control knobs set in a formation of Boston and the control lever in "exact" position, only the policies 45 issued to holders residing in Boston will be tabulated, sorted, etc. So also, by means of the "State" control knobs, a larger district, say, "Penn", may be taken under control for recording. 50

From the above examples of the use of the machine applied to the insurance business, only a few adaptations of this flexibly controlled machine may be observed. At any time during its 55 operation, and regardless of the position of the control knobs, printing or no printing may be had by setting the control lever to either of those positions. The controls may also be used in combination where a plurality of characteristics of the data, any one of which is a desired controlling factor, are wished to exercise control at the same time. An example of this would exist when there are set in controlling positions the control knobs for a certain agent and a certain date. Then not only would control be governed by the 60 one characteristic, the agent, but the date of the data presented would also exercise control. 65

As may be noticed above, not only for statistical insurance work is this machine under effectual controls, but for other business processes, such 70 as making bills and keeping records, accumulating amounts of accounts receivable, etc., it is also above the ordinary in usefulness.

It is assumed in all of the foregoing examples 75 of statistical control, that the accumulation in

the totalizers is also under control. This, however, does not have to be so, because the control over accumulations is optional and is only effective upon depression of an accumulator control key which protrudes near the rear of the machine.

The ordinary total taking functions of this machine have been discussed hereinbefore, but the machine is capable of other novel usefulness 10 when total taking is done under control of the control section. This is accomplished by depressing the accumulator control key at the same time a total key is depressed. When total taking is done under control, it is possible to change, 15 during operation of the machine, the function of total taking to sub-total taking, or sub-total taking to total taking, the change being made when the amount standing in the totalizer selected does not satisfy the control amount that is set up by 20 the amount control knobs and the control lever. To take an example, let us say that the agent's commission is figured every month from the receipts of the month for which the agent is responsible, and that another condition is that no 25 agent shall receive commissions on receipts of less than \$200, but that the amount of receipts, even though they are less than \$200, will be retained in the account of the agent for the next month when commissions will again be figured. 30 To do this in the machine all that it is necessary to do after shifting the selection lever to the position of the desired agent and depressing the total key, is to depress the accumulator control key, set up \$200 on the amount control knobs, 35 position the control lever in "below index" position and operate the machine. Then, if that certain agent's totalizer contains less than 200 the item will be printed, but instead of a total being taken, a sub-total will take place, and the 40 amount will be retained in the totalizer.

The control may also be exercised by amounts above or larger than the set up amount. The agents may be rewarded with a bonus if receipts for a month are larger than \$3000. Also the size 45 of the bonus may depend on the amount of the receipts over \$3000. To retain all amounts over 3000 in the totalizers for later reference, all that is required when taking a total, besides selecting the desired totalizer and depressing the total key, is to depress the accumulator control key, set up 3000 on the amount control knobs, put the control lever in "above index" position and operate the machine. If the amount in the totalizer is more than 3000 a sub-total will take 50 place and the amount will remain standing on the totalizer wheels instead of being cleared out.

The novel way of changing the functions as outlined above may also be secured with the control lever in either "exact" or "between index" positions when a problem is presented for such a condition.

A control may also be had during sub-total taking for changing this function to total taking and clearing out whatever amount is in the totalizer. This control may also be of the forms "above", "below", "exact" or "between index". An incident of such a use follows:

It may be assumed that throughout the year 70 the monthly receipts of the agents are recorded and punched cards made so that tabulation may be had at the close of the year. At this time, after clearing the totalizers of the last month's receipts, all the receipts of the year are accumulated into the totalizer. It is wished at this time 75

that any agent not doing business throughout the year of at least \$2,500 will have his agency taken away from him. With that purpose in view, the sub-total key is depressed, the selection lever is positioned and then the amount control knobs are set to 2,500, the control lever is put at "below index", the accumulation control key is depressed and the machine is operated. Upon operation, if the amount in the totalizer is less than 2,500, the item will be printed, making a 10 record of agents to be discharged, and instead of a sub-total being taken as intended, the totalizer will be cleared to zero and so will be in condition to receive a new account. With all the above outlined conditions in force, but the control 15 lever being in "above index" position, upon operation of the machine, a printed record of the retained agents having over 2,500 will be had, the sub-total changing to a total, clearing the retained totalizer. 20

When the machine is being operated under the influence of the control section, and an item is printed or accumulated because of said influence, the card associated with the item will be sorted aside from the cards having data which 25 did not satisfy the requirements of the control set up. This sorting occurs automatically and at the same time as printing and accumulating. The cards thus sorted may be separately tabulated in the machine for a record or may be filed away 30 for future reference.

The machine may very well be employed in other classes or fields of business, for example, banking. Minor changes in construction may be necessary but nothing involving skill. We will 35 take for a concrete example that 500 checking accounts are to be taken care of. The minimum amount allowed to stand in an account is to be \$200. If the account falls below this figure during the month a charge is to be made at the 40 end of the month. Also, daily slips will be printed of accounts overdrawn. Amounts will, of course, be added and subtracted at different times from the amounts in the accounts. At the end of 45 every business day the amount standing in each account is to be noted so as to detect overdrafts or accounts lower than \$200.

To meet these requirements, the machine will have 500 totalizers, one for each account, of a form as shown, and connections are made 50 from each of them to the amount racks. The means for controlling the actuation of the totalizers may be punched cards as shown, or a keyboard may be provided for setting up the data. The printing and controlling sections may be 55 used just as described hereinbefore. During the day, the amounts on checks drawn on a certain account are subtracted (by complements) from the related totalizer, while deposits made in the same account are added to the totalizer. At the 60 end of a day or any period, all the overdrawn accounts will have an abnormally large amount standing on the totalizer, a figure such as 99.947 showing that the account has been overdrawn \$53. This overdraft can be noticed immediately when the check causing the overdraft is tabulated in the machine, if the items printed on the record strip are noted through a window in the case. But if wished, at the end of the day, a printed list and printed sheets of all overdrawn accounts 65 may be had at once. To do this, the amount control knobs are set at 90,000, the control lever is set at "above index", the accumulation control key and sub-total key are depressed and the machine is operated between successive selections 70 75 923

of the totalizers. Then, as sub-totals are taken of the different totalizers, if one comes along upon which more than \$90,000 is present, the control will be exercised and will print an extra slip and change the sub-total to a total, clearing that totalizer. If desired, the sub-total may be taken and the amount remain in the totalizer by releasing the accumulator control key. After all 5 500 accounts have been selected, the overdraft 10 slips may be gathered and noted and used as notices to the account holder, of the state of his account.

It may be a question whether the large amount of 99,947 is a large deposit or an overdraft of 15 \$53. Of course, with this control it is assumed that no one would put more than \$90,000 in a checking account and that no one would overdraw his account more than \$10,000. For larger 20 accounts in which this may occur a few more denominational banks added to the totalizer would dispel any doubts as to whether a large amount on the totalizer was a deposit or an overdraft.

Now, I also wish to detect any account having 25 less than \$200 on the related totalizer at the end of a day. To do this the amount control knobs are set to 200, the control lever is put in "below index" position, the sub-total key is depressed, and the machine is operated between successive 30 selections of the different totalizers. Any account that has less than \$200 will then effect the printing of a slip. The slip will, of course, have imprinted upon it not only the amount standing in the totalizer but also a designation (by 35 number or name) of the totalizer selected. The slips can be filed for reference at the end of the month. At this time, the slips may be used in accordance with the custom of the bank. Some banks may make a charge for any account falling 40 below \$200 no matter how seldom this happens or how small the shortage. In that case, every account for which a slip has been issued during the month should be charged. Upon reference to the accumulation of slips for a month, 45 the information sought may be easily found. Other banks may only make a charge if the average amount in the account throughout the month falls below \$200. In this case all the issued slips must be referred to. Taking all the 50 slips of a certain account that have been issued throughout the month, noting the amounts thereon, adding them together with the amounts recorded daily on the record strip, then dividing by the number of days in the month will give the 55 average amount in the account during the month. Of course, accounts from which no slips have been issued throughout the month will not be considered because they have never fallen below \$200. Also, accounts having but one or two slips 60 with small amounts below \$200 may be disregarded.

In the making of monthly statements the machine may also be useful. It may be assumed that the old balance is recorded at the head of a new 65 statement sheet with the designation of the account. This can be done at the end of a month by the machine set to take an ordinary subtotal. At the end of the first day in the month the old balance is noted and the amount set up 70 on the control knobs, the control lever is moved to "exact" position, the related totalizer is selected, sub-total key depressed, and the machine operated. Every totalizer having an amount similar to its old balance will print a slip showing 75 that no transactions in the related account

have been made during the day. If a slip is not printed, however, the control lever should be moved to either "above index" or "below index" until a slip is printed. This slip will show a difference of the account over the old balance, and 5 this difference may thus be noted on the statement sheet. With the machine set to take a subtotal under "exact" control without printing, and then take a total with printing, this machine could be made to no-print the amount if it is 10 exactly the same as the old balance and print when it is different. The statement sheet may be used as an inserted slip so that printing of change in account would be done directly on the statement. These two changes would increase the 15 speed of making the statement record.

In Government work there are many conditions where use may be made of the novel features herein disclosed. This may include payroll, census and statistical work. The statistical work would 20 involve examples somewhat like those given hereinbefore in adapting the machine of this invention to an insurance business. The census tabulations would be expedited in no small measure by the ability of this device to simultaneously 25 pick out any one of a select group of characteristics for tabulation. For example, recording of data concerning people between ages of 10 to 20 or 20 to 30, etc., or data relating to manufacturing establishments having a capital between 30 \$50,000 to \$60,000, etc., can be selected, printed and sorted simultaneously and without necessitating separate selection for each characteristic. Tabulation according to each individual characteristic can be had, of course, when desired. The 35 increased data-holding capacity of a standard sized card is also a decided advantage in enabling the coding of a complete record of names, dates and numbers on a single card.

In large stores having merchandise that is 40 sold on the installment plan, many uses of the present machine may be developed. For example, each opening installment account may be given a totalizer. These totalizers may be grouped according to the amount, all in a group 45 having the same amount received every month. As installments are paid they are added in the totalizer. The bills requesting the installment payments may be made in a manner similar to the printing of the insurance bills noted hereinbefore. 50 When the amount in an account falls below the required standing of the group, the control mechanism in "below index" position will control printing to issue the bill.

The above description is a general outline of 55 some of the objects and uses of the machine observed from a broad viewpoint. The several sections of the machine will now be described in detail with reference to the drawings which accompany and form a part of the specification. 60

Fig. 1A is a side elevation view of the forward portion of the machine showing the operating connections for the printing, controlling and paper feed mechanism.

Fig. 1B is a continuation of Fig. 1A and is a 65 side elevation view of the rearward portion of the machine showing the card feeding, sensing and sorting mechanism, also the motor and connections to the operating mechanism for totalizer engagement and other devices. 70

Fig. 2 is a view of a perforated record card. It is perforated as a card would have to be to actuate the machine and print a record as shown in Fig. 20.

Fig. 3 shows the different combinations of 75

holes possible with five holes. It also shows the number of steps of movement given the actuators of the machine, and the corresponding alphabetic and date printing positions of the actuators for each combination of holes.

Fig. 4 shows the different combinations of holes possible with four holes. It also shows the number of steps of movement given the actuators of the machine for each combination of holes.

Fig. 5 is a side elevation of the mechanism for converting the depression of four rods, in a jacquard mechanism sensing four holes in a card, in different combinations, into sixteen different extents of movement of a type bar and totalizer actuator.

Fig. 6 is a side elevation of the mechanism for converting the depression of five rods in different combinations into thirty-two different extents of movement of a typebar containing type for printing letters, dates, or numbers.

Fig. 7 is a side elevation showing the arrangement of three of the mechanisms shown in Fig. 5 so as to be able to operate all three from a single bank of 12 rods in the connection box of the jacquard mechanism.

Fig. 8 is a side elevation showing the arrangement of two of the mechanisms shown in Fig. 6 so as to be able to operate both from a single bank of 10 rods in the connection box of the jacquard mechanism.

Casing and framework

In Figs. 1A and 1B there is shown one side of the main frame of the machine which serves to support most of the various mechanisms to be described. This frame is composed of right side frame 50 and a left side frame 51, each near its respective side of the machine. The space between the frames may be provided with intermediate bracing frames if additional support for the cross shafts and bars is desired. Many of the cross shafts use the two side frames for bearings while other shafts and bars are fixed in the frames and act as tie rods. The two vertical frames are secured to and supported by a base plate 52. This base plate extends beyond the frames and may be provided with legs so that it forms the platform of a table or it may be left plain without legs, in which case the machine would be placed on another table for operation.

The machine is constructed so that the bulk of the operating parts are located between the two side frames 50 and 51, although at each side there is an overhang of certain portions of the mechanisms including a number of the main through shafts. It will be apparent as the description progresses that wherever possible the various distinct features of the machine have been constructed as individual units having their own supporting frames which are separably mounted and secured in place on an appropriate portion of the main supporting structure.

The frames 50 and 51 extend at the rear (Fig. 1B) to support the card feeding, sensing, and sorting mechanism counted on the rear of the machine.

A casing 53 covers most of the machine, leaving an open space for the insertion of the record cards. The case also has apertures through which the controlling keys are depressed and the levers are rocked. A hinged cover plate 54 in the case when lifted gives access to the record material which may then be removed and replenished.

Main operating mechanism

In the following description, the operating connections will be traced from their source up to the point of application. The application of the driving parts will be described further on in connection with the mechanism with which they are used. Mounted on the base 52 is an electric motor 55 (Fig. 1B) the shaft 56 of which extends into a gear reduction unit 57. This gear reduction device may consist of the usual worm on the motor shaft with a cooperating worm wheel. Connected to the worm wheel is one side of a clutch, the other portion of the clutch being attached to a drive shaft 58. The clutch is housed in a portion 59 of the frame 57. Although not shown, it is assumed that all the usual adjuncts of the above mentioned operating devices will be furnished, such as a switch for the motor, an operating bar for the clutch which may be held down for continuous operation of the machine or touched for single operations of the machine, and an inter-

lock preventing operation of the clutch during operation of a controlling key or vice versa. Also attached to the drive shaft 58 is a gear 60 and a chain sprocket 61. The gear 60 is in mesh with a gear 62, and actuates this gear through a single revolution upon each operation of the machine. The gear 62 then transmits its motion to similar sized gears 63, 64, and 65, which contain operating cams and projections for actuating the various devices shown in Fig. 1B. For the purpose of transmitting the motion of the operating shaft 58 to the front of the machine, a chain 66 is secured around sprocket 61 from which it runs forward to a sprocket 67 loosely mounted on a stud 68 in side frame 50. Attached to the sprocket 67 is a gear 69 having a cam groove for operating the control mechanism. This gear 69 is in mesh with another gear 70 which is loosely pivoted on a stud 71, in the right side frame. Gear 70 has attached thereto a cam 72 for operating a preliminary control device; also attached are two mutilated gears, the gear 73 has a single group of teeth 74 for operating the printing mechanism, the other gear 75 has two groups of teeth 76 which actuate the paper feeding devices.

Card handling devices

The following section of this specification deals with the means for holding, feeding, sensing and sorting the record cards employed in the machine.

A box 77 (Fig. 1B) is secured to the rear extensions of the side frames 50 and 51. Fastened in the box is a shelf 78 upon which rests the record cards 79 and a follow up weight 80. The weight 80, by means such as a spring or weighted pulley, keeps the record cards before its face, frictionally held against a plate 81. Between the plate 81 and the shelf 78 is an open space through which only one card may pass at a time. When fed through this space, the card falls into the sensing mechanism between plate 81 and a pin frame 82 where the card is supported upon a latch 83.

A train of operating parts is provided which is driven by the main operating mechanism. They are utilized for the purpose of feeding a card from the holding devices into the sensing mechanism.

Mounted on the side of the gear 63 is a pin 84 which, upon every revolution of the gear 63, acts upon the cam face of a lever 85 to rock the lever in a clockwise direction. The lever 85 is fastened to a shaft 86 which has a bearing in the side frame 50 and extends through to the inside of the machine. On the inside of the machine an arm 87 is fastened to shaft 86. At the end of the arm is pivoted a link 88 which serves as a connection to a long lever 89 which is pivoted on a shaft 90. A spring 91 stretched between lever 89 and a stud on the side frame serves to hold the parts in normal position. Operatively connected to the end of lever 89 by a pin and slot connection is a sliding pawl 92 which has a short finger overlying the record card that is next to the plate 81. The pawl 92 is suitably held on the plate 81 so that it may slide vertically down the plate and carry before it a record card. From the above description it is apparent that every time the machine is operated, the lever 89 is oscillated, sliding the pawl 92 down the plate 81 and feeding a card into the sensing mechanism. After the pin 84 passes the high point on the cam face of lever 85, the spring 91 restores the parts, lifting the pawl 92 so that its finger overlies the next record card in the pack on the shelf 78.

A sensing mechanism is provided for the purpose of operating a jacquard device in accordance with the holes punched in code on the record card. By means of this mechanism the holes in the card are used to determine which of the rods 5 in the jacquard device are operated.

A pin frame 93 extends across the machine between the frames 50 and 51. In the pin frame are flexibly mounted a plurality of rows of sensing pins 94. Each of the pins is provided with a 10 spring (not shown) which holds the pin extended out of the frame 93. Rollers 95 are mounted on the sides of the pin frame for supporting it in slots 96 on the insides of side frames 50 and 51. The slot is longer than the distance between 15 the rollers on the frame, thus allowing the frame to reciprocate back and forth horizontally. To operate the connections for reciprocating the pin frame, a cam groove 97 is cut in the side of gear 63. A bell crank 98 is pivoted on a stud 99 and 20 has, on the end of one arm, a roller which protrudes into the cam groove 97. On rotation of the gear 63, the bell crank 98 will be oscillated first in a counter-clockwise direction and then in a clockwise direction back to normal position. 25 This motion of the bell crank is transmitted to the pin frame by a link 100 extending between the vertical arm of the bell crank and an arm of a lever 101 pivoted on a stud 102 in the right side frame. The other arm of the lever 101 is 30 slotted to receive a roller 103 on the pin frame 93. By means of the above connections, it is plain that during the early part of the movement of gear 63, pin frame 93 will move towards the record card held between plates 81 and 82, and 35 during the final portion of the rotation of gear 63, the pin frame will withdraw the pins from the card. When the pin frame moves towards the card, the sensing pins will sense the card and wherever there is a hole in the card the pin will 40 reach through and move the related connection rod a, b, c, etc., in the jacquard frame. If an unpunched portion of the card is presented before a sensing pin, it will be obstructed and the spring in the frame 93 will be compressed and 45 the related connection rod a, b, or c will not be moved. After the card has been sensed and the pins 94 are withdrawn from the card, the latch 83 is withdrawn allowing the card to fall into the sorting bins. The operating connections to 50 the latch 83 will now be described.

Protruding from the side of the gear 63 is a pin 104 which, during the final part of the revolution of gear 63, strikes a cam face 105 on a bell crank 106 pivoted on a stud in the side 55 frame. Attached to a depending arm of bell crank 106 is a connecting link 107 which reaches rearward and is connected to an arm 108 secured to a shaft 109 journaled in the side frames. To this same shaft 109 is connected the latch 83. A 60 spring 110 holds the parts in normal position and restores them to the said position. It is clear that by the above means, near the end of the operation of the machine the latch 83 will be oscillated allowing the card to fall into the 65 sorter.

The sorter is shown in the drawings with only two bins, but an unlimited number of bins are contemplated, for the mechanism disclosed does not have to be confined to the specific showing. 70 The bins are numbered 111 and 112. The card will normally fall into bin 112, being guided in this course by a guide plate 113 and a separating plate 114, both of which extend across the width of the sorter. However, under certain conditions 75

in the machine, the card may be sorted from the rest so as to fall into bin 111. The means for doing this comprises a shaft 115 which is in line with plate 114 and extends across the sorter, being mounted in bearings in the side frames. Secured to this shaft is a moving separator plate 116 which extends across the sorter and swings with shaft 115 as a center. This upper plate 116 normally lies as shown in full line on Fig. 1B. It then appears as a continuation of plate 114 leaving no space between it and the plate 81 of the frame. However, if shaft 115 is rocked clockwise a small extent, plate 116 will assume the dotted line position of Fig. 1B, with its upper end contacting plate 113, thus directing the cards into bin 111. The means for rocking the shaft 115 will be described further on in this specification.

The foregoing section of the specification deals with the card handling devices of the machine, so at this point in the specification it may be explained how the card is punched for use in the machine.

Fig. 2 shows a sample record card 79 of regular commercial size which is punched in the code required by the jacquard mechanism in the present invention. The specific punching shown is that which is necessary to control the machine so that the statistical sheet shown in Fig. 20 will be printed. It will be noted that the groups of holes on the left hand side of the card are four holes in height and that three groups of holes may be placed one above the other, each group using four of the twelve holes in the vertical rows. The four holes in a vertical row are adapted, by means to be described, for controlling the positioning of an actuator in one of 16 positions. The groups of holes on the right hand side of the card are five holes in height and two groups may be placed one above the other with a horizontal space between. The vertical space on the card between the groups of four and the groups of five holes is provided to allow room in the jacquard device for division plates which support the ends of the shafts in the two sections of the jacquard. It is apparent that, even with the large amount of data printed on the sheet shown in Fig. 20, the full capacity of the card has not been used.

In Fig. 2 the space allotted to each related group of holes is encircled with a fine line. These groups are named and numbered. The amount group 117, the age group 118, the agent group 119, and the number group 120, are shown on the left hand side of the card. The operator group 121, the date group 122, the first name group 123, the last name group 124, and the state group 125 are on the upper right hand side of the card; while the occupation group 126, policy number group 127, street number group 128, street name group 129, and city group 130 are on the lower right hand side.

If desired the data may be printed on the card at the time they are punched. This would obviate the necessity of decoding the combinations on the card when it is required to read the card as is sometimes done in certain classes of work.

Fig. 4 shows all the different combinations of four holes which may be punched in the card, with the corresponding actuator position lettered below each combination. There are sixteen actuator positions, thus providing room for a zero type and fifteen numeral type on the printing portion of the actuator. The totalizer operating

portion of the actuator is adapted to rotate the totalizer wheel through fifteen steps of movement. Of course, this much movement is not always needed. In the English money system using pence, eleven steps of movement are needed; while the American money system, or the decimal system, requires only nine steps of totalizer wheel actuation. So it is apparent that the number of steps of actuator movement are more than enough as far as totalizer actuation is concerned. The connection rod designating letters *w*, *x*, *y*, and *z* have been placed in line with the holes with which the related rod would cooperate on a card.

Fig. 3 shows all the different combinations of five holes which may be put on the card, with the corresponding actuator position lettered below each combination. These actuators, as shown in the present machine, are used to position a type section and not to actuate a totalizer, although they could do so if desired. There are thirty-two actuator positions, thus providing room for a blank type and thirty-one other types on the printing portion of the actuator. This printing capacity just meets the requirements of printing the day of the month in date printing. Of course, the printing capacity is more than that required for printing the 26 letters of the alphabet and the 12 months of the year. These various date, number, and alphabet type are shown in Fig. 3 in vertical alignment with the combination of holes necessary to secure their selection for printing. The letters *a*, *b*, *c*, *d*, and *e* have been placed in horizontal alignment with the holes with which the related connection rods would cooperate, were the holes present on a record card.

Jacquard or decoding mechanism

The naming of this portion of mechanism as a jacquard mechanism is not intended to limit the device to one operated only from punched record media. The structure is adapted to be employed in a machine wherein the data presented may not only be in the form of a hole in the record media but may also be in the form of embossings, metal inserts, etc., on a record. The name "jacquard mechanism", as interpreted in this specification, is intended to mean a decoding mechanism which is adapted to convert combinations of record indications (not necessarily punched holes) into distinct and different extents of operation of devices (not necessarily accounting devices) under its control.

As may be inferred from the description of the record card, there are disclosed herein, two forms of this jacquard device. One is under the control of combinations of four holes and the other form under the control of five holes. In both forms the same principle obtains and this principle may be expanded to employ the use of more than five holes in combination. In the illustrative showing the two forms of jacquard devices are used and they are provided with a common connection box for housing the connection rods *a*, *b*, and *w*, *x*, etc., previously mentioned.

This connection box (Figs. 5, 6, 7, and 8) comprises spacing plates 131, 132, 133, 134, and 135 in which are the holes for guiding the connection rods. These plates are held in place by two side plates 136, only one of which is shown in Fig. 5, and a center plate 137, Fig. 6. The whole connection box is removable as a unit. It is contemplated that the side plates have fixed lugs or studs for sliding in locating slots in the main

side frames. The box would slide out of the back of the machine after the removal of the sorter and the sensing devices.

In Fig. 5 is shown the form of mechanism controlled by four punched holes in combination on a record. The view is a section showing one column of the connection rods and the mechanism cooperating with the four top rods which cooperate with the holes in the amount group 111, 5 Fig. 2, on the record card 79. Each of the rods *w*, *x*, *y*, and *z* has a spring 138 for restoring it to normal position, and a stop 139 for holding it there. When a sensing pin 94 is inserted through a hole in the record card it will slide the related 10 connection rod to the left in Fig. 5. The left end of the connection rod then pushes a stop pawl which normally holds a rack from movement. There are two layers of such stop pawls cooperating with each bank of four rods, see 15 Fig. 18. The parts for the one bank are confined in the plane of these two pawls. A thin spacer 140 is provided between adjacent pawls and racks to space and guide them in their movement.

20 When the rod *w*, Fig. 5, is operated, it will rock the pawl 141 pivoted on the shaft 142 which extends between the main side frames. This pawl 141 normally abuts the end of a rack 143 slidably mounted on a rectangular bar 144 that extends between the side frames. A pair 25 of combs 145 fixed to the bar, guide the rack and hold it in vertical position. The end of the slot in rack 143 is exactly one tooth space of the teeth on the rack, away from the side of the 30 comb 145 so that at the proper time, if the pawl 142 is rocked out of the path, the rack 143 will be able to move one tooth space to the left.

35 In a similar fashion, operation of rod *y* will rock a pawl 146 also pivoted on shaft 142 and separated from pawl 141 by spacer 140. This pawl 146 cooperates with rack 147 alongside of, and somewhat similar to rack 143, the only difference being that the end of the slot in rack 147 is two tooth spaces away from the side of 40 comb 145.

45 The operation of rods *x* or *z* produces a somewhat different effect. A pawl 148 pivoted on a shaft 149 has pivotally mounted on one end, a bell crank 150 one arm of which abuts the end 50 of rod *x* while the other arm is in front of rod *z*. Thus, it is apparent that if either rod *x* or rod *z* is operated alone, the bell crank 150 will rock about the end of the other rod as a fulcrum, and in turn rock pawl 148 half the distance that it would be rocked were both rods *x* and *z* operated simultaneously. Thus it is clear 55 that pawl 148 can be rocked to two extents, a small angle of movement by operation of one rod, and a larger angle of movement when both rods are moved together. The horizontal arm of pawl 148 reaches to the right of shaft 149 and cooperates with a rack 151 slidably mounted 60 on a rectangular bar 152. Both bar 152 and shaft 149 are mounted in the main side frames. 65 The rack 151 is nearly all hidden by a somewhat similar rack 153 which is before it in Fig. 5. The end of the slot in rack 151 is eight tooth spaces from the comb on bar 152 so that if released for movement it can slide that far. But, if pawl 148 is only rocked the small amount it will, upon movement of the rack, engage an extension 154 on rack 151 and only allow the rack to move four steps instead of eight. The 70 eight steps of movement of rack 151 are only

allowed when the pawl 148 is rocked the larger amount by joint operation of rods *x* and *z*.

Another pawl 155 is offset to the side of crank 150 and is adapted to be operated by rod *z*. This pawl also pivots on shaft 149 and has a forwardly 5 extending arm normally abutting the end of a rack 153 which has a slot guiding it on bar 152 and allowing it to move four tooth spaces. It will be noticed that operation of rod *z* alone will rock both pawls 148 and 155 releasing racks 151 10 and 153 so that each may move four steps.

15 At this point it may be well to point out bars 156 and 157 extending between the main side frames. Upon these bars there are fixed leaf springs 158 and 159 which have extensions bearing 20 upon each pawl tending to keep the pawl in normal position.

Extending alongside the pawls 148 and 155 is a shaft 160 which is mounted in bail arms 161 that are fixed to each side of shaft 149. A slight 25 clockwise movement of shaft 149, will, through the above devices, swing the ends of pawls 148 and 155 out of the path of racks 151 and 153. This occurs only during total taking and is described more fully further on in the specification. 30 In a similar arrangement, shaft 162 and bail arms 163 pivot on shaft 142 and are connected to bail arm 161 by a link 164. Thus, pawls 141 and 146 are rocked to release racks 143 and 147 simultaneous to the release of racks 151 and 153. 35

For the purpose of restoring and governing the time of movement of the four racks 143, 147, 151, and 153, there is provided a restoring ball. This ball consists of two arms 165, fixed to shaft 166, having two shafts 167 and 168 extending between 40 them. A counterclockwise movement of shaft 166 will move arms 165 to the left, Fig. 5, rocking shaft 167 away from racks 151 and 153, and shaft 168 away from racks 143 and 147. Subsequent clockwise movement of shaft 166 will restore all 45 the racks to their normal position. The shaft 166 is mounted on bearings in the two main side frames and extends from the right frame for operation.

50 The operating connections for the ball are shown on Fig. 1B. The front shaft 166 extends from the side frame and has fixed to its end an arm 160' to which are attached two links 161' and 162'; the one link 161' serving to connect the various shafts 166 together, and the other forming an operating connection to an oscillating bell crank 163'. The four other shafts 166 have secured thereon, arms 164' to which links 161' are pivotally connected. Two of the shafts 166 extend from the right side frame and are connected to the right end of the front shaft 166. The other two shafts 166 extend from the left side frame and are connected to the long front shaft by a link similar to link 161' shown. The crank 163' is operated by a box cam 165' on gear 60 64. A roller 166' on one arm of the crank extends into the groove of said cam.

65 From the foregoing it may be gathered that there are four racks under control of a bank of four rods and that each of the racks has a different extent of movement, namely, one, two, four, and eight steps of movement. It will be noticed that each extent of movement is a factor or divisor of 16, the largest number of combinations or different extents of movement possible 70 with four record characteristics in combination. This novel principle will also be discussed in connection with the five hole combination in the record card.

75 The devices about to be described are provided

for the purpose of summing up or adding together the simultaneous movement of any number of the four racks and imparting this movement to a single actuator. These devices are adapted to transmit the movement of a single rack, or movement of any combination of the four racks, to the actuator.

For the purpose, a novel form of differential gearing is employed. A pinion 169, Fig. 5, 10 meshing with opposite racks 143 and 153, is pivotally mounted by a stud 170 on a rack slide 171, see also Fig. 19. A similar pinion 172 meshing with racks 147 and 151 is similarly mounted on another rack slide 173. These rack slides are 15 held in place and slide on rectangular bars 174 and combs 175 between frames 50 and 51. It is apparent that the pinions may rotate, or move bodily without rotating, or have a combined translative and rotating movement. If rack 143 is 20 held immovable while rack 153 moves four tooth spaces, then pinion 169 will have a differential movement and will rotate two tooth spaces, meanwhile translatively moving stud 170 two tooth spaces to the left, carrying slide 171 along. If 25 rack 153 does not move while rack 143 moves one tooth space, then pinion 169 will rotate and carry slide 171 one-half of a tooth space to the left. If both racks move in the same direction, for the first tooth space of movement, pinion 169 will not 30 rotate, but will move with rack slide 171 one space to the left. When rack 143 is stopped and rack 153 continues to move three more steps, the pinion will receive a differential motion of one and one-half steps of rotation and one and one-half steps of translation. From the foregoing it 35 is clear that whatever the combined movement of racks 143 and 153 is, rack slide 171 will be moved exactly one-half that amount, namely; zero, one-half, two or two and one-half tooth spaces.

40 In a similar way, rack slide 173 will have imparted to it through pinion 172, exactly one-half the combined movement of racks 147 and 151. Therefore, rack slide 173 will move zero, one, four, or five tooth spaces to the left.

45 It is noticed that rack slide 173 has a depending arm 176 which is provided with rack teeth opposite to the rack teeth on the end of slide 171. A pinion 177 cooperates with the rack teeth on rack slides 171 and 173 in a manner similar to the co-operation of pinion 169 on 172 with the racks. This pinion 177 is pivotally mounted on the end of a rack slide 178 which is guided vertically and horizontally by the bars 179 and combs 180 between frames 50 and 51. A tension spring 181 50 between a fixed rod 182 and the end of rack slide 178 urges the rack slide to the left, Fig. 5. The tension in this spring is transmitted through the rack slides and pinions over to the four racks urging them to the left and moving them when 55 the pawls and bail 165 allow. Since the relation between rack slide 178 and rack slides 171, 173, is the same as the previously described relation between rack slide 171 and racks 143, 153, it is believed apparent that rack slide 178 will receive 60 exactly one-half the combined movement of rack slides 171 and 173. And since the movement of slides 171 and 173 is only one-half of the original combined movement of the four racks, and the movement is reduced again by half in transmission 65 to slide 178, it is clear that rack slide 178 is moved to the left one-fourth of the combined amount that the four racks are allowed to move. This movement is one-fourth of, zero to fifteen tooth spaces, or zero to three and three-fourths tooth 70 spaces on rack slide 178. So that now if the 75

movement of rack slide 178 is multiplied four times, a single member will have a movement equal to the combined movement of the four racks. That is the purpose of pinion 183 and segment 184.

5 A shaft 185 fixed in the main side frames has loosely mounted thereon a pinion 183 to which is attached a segment 184, the gear teeth of which are formed on a pitch circle four times the diameter of the pitch circle of the pinion. The gear 10 teeth of pinion 183 mesh with rack teeth 186 on rack slide 178 so that movement of rack slide 178 to the left will rock segment 184 in a clockwise direction. This movement of segment 184 is transmitted to an actuator slide 187 by means of 15 rack teeth 188 on the slide. From the foregoing it is apparent that each actuator 187 is operated under control of the differential gearing to receive a movement ranging from zero to fifteen steps depending upon the combinations of related rods *w*, *x*, *y*, and *z* that are operated.

These actuators 187 have many uses in the machine that will be explained as the specification continues. Since they are the amount actuators, they have rack teeth 189 for actuating the 25 totalizers. Rack teeth 190 are provided for holding the actuators while totals are being taken. These rack teeth could also serve in connection with a detent for giving the actuators a final adjustment for printing alignment. For the purposes mentioned there are shown cooperating with the teeth 190, pawls 191 which are loosely pivoted on shaft 192 with attached springs 193 tending to engage the pawls with the rack teeth. A bail fixed to shaft 192 consisting of arms 194 30 and a cross rod 195 normally holds the pawls out of engagement with the actuator. On every operation of the machine, and at the proper time during the taking of a total, the bail allows the pawls to rock into engagement with the actuator. 40 The shaft 192 extends beyond the right side frame 50, Fig. 1B, and has an arm fixed to its end. A link connects this arm to the midpoint of a lever 196 pivoted on the side frame and carrying a roller which cooperates with a cam face 45 197 cut on the side of gear 65. A spring 198, Fig. 5, connected to bail 194, serves to keep the roller in constant cooperation with the cam 197. This cam is so proportioned that after the actuators 187 have been adjusted, the pawls 191 engage 50 the teeth 190 and prevent further movement of actuators 187 to the right which would otherwise occur during total taking since then the actuators are free for movement under control of the totalizer wheels, and when released therefrom 55 would tend to slide to the extreme right. The actuators may be moved to the left, however, for then the pawls 191 merely ratchet over teeth 190.

The form of jacquard device under the control of five holes in combination on a record will 60 now be described. The connection rods, *a*, *b*, *c*, *d*, and *e*, Fig. 3, for this device are mounted in the same connection box discussed above, the relative position of the rods being obvious from the position of the holes in the record card, Fig. 2, 65 and from the diagrammatic showing of both sections of the box in Figs. 7 and 8. As the construction and mode of operation of this jacquard device is quite similar to the one already discussed, the description will not have to be as 70 much in detail.

In Fig. 6 is shown the form of mechanism controlled by five holes in combination on a record. The view is a section showing one column of the connection rods with one cooperating mechanism. 75

- The rods have springs 138 for restoring them to normal position. The left end of the connection rods cooperate with stop pawls that normally hold racks from being moved. The four stop pawls provided for each bank are arranged in two planes or layers and the pawl ends cooperating with the rods are positioned to cooperate in two lines against the ends of the bank of five rods, as in the case of the four rods, see Fig. 18. 5
- 10 The pawl ends must be offset over or under each other as shown to keep within the space of the two planes of parts. The spacers 140 shown in Figs. 5 and 18 may also be provided to guide and space the racks and pawls in Fig. 6.
- 15 When the rod *a*, Fig. 6, is operated, it will rock a bell crank 200 which is pivoted on a stop pawl 201 that is mounted on shaft 202. This bell crank 200 has a short arm cooperating with rod *a*, and an arm twice as long cooperating with rod *d*, so that when movement of rod *a* rocks the crank, using the end of rod *d* as a fulcrum, pawl 201 will be pushed twice as far as when rod *d* rocks the crank with the end of rod *a* as a fulcrum; thus giving stop pawl 201 two different 20 extents of movement according to which rod is operated. This pawl will get a third and still further extent of movement when both rods *a* and *d* are operated together. Stop pawl 201 normally abuts the end of a rack 203 slidably mounted on a rectangular bar 204 that extends between the main side frames. A pair of combs 205 held on the bar, guide the rack and hold it in vertical position. The end of the slot in rack 203 is exactly three tooth spaces, of the teeth on 25 the rack, away from the side of the comb 205, so that if the pawl 201 is rocked completely out of the path of rack 203 it will move three tooth spaces to the left. However, stop pawl 201 does not always rock completely out of the path of 30 the rack, but has three extents of movement; rack 203 has a shoulder 206 allowing it to move one tooth space when pawl 201 is rocked a slight extent by rod *d*, and a shoulder 207 allowing it to move two tooth spaces when pawl 201 is rocked 35 by rod *a*. When pawl 201 is rocked still further by operation of both rods, it completely clears the rack, allowing the rack to move until the end of the slot abuts comb 205.
- The operation of rod *b* rocks a stop pawl 208 40 that is also pivoted on shaft 202. This pawl 208 normally prevents movement of a rack 209 which is slidably mounted next to rack 203 on bar 204. The slot in rack 209 is long enough to allow a movement of four tooth spaces.
- 45 The operation of rod *c* or *e* produces a somewhat different effect. A pawl 210 pivoted on shaft 211 has pivotally mounted on the end of one of its arms, a bell crank 212, one arm of which abuts the end of rod *c* while the other arm is in front of rod *e*. It is apparent that if either rod *c* or rod *e* is operated alone, the bell crank 212 will rock about the end of the other rod as a fulcrum and rock pawl 210 half the distance that it would be rocked were both rods *c* and *e* operated simultaneously. Thus it is clear that pawl 210 can be rocked to two extents, a small angle of movement by the operation of one rod and a larger angle of movement when both rods are moved together. The upper arm of pawl 210 reaches to the right of shaft 211 and cooperates with the end of a rack 213 slidably mounted on a rectangular bar 214. Both bar 214 and shaft 211 extend between the main side frames. The end of the slot in rack 213 is sixteen tooth spaces 55 from the comb on the bar 214, so that if released

for movement it can slide that far. But if pawl 210 is only rocked the small amount it will, upon movement of the rack, engage an extension 215 on rack 213 and only allow the rack to move eight steps instead of sixteen. The full sixteen steps 5 of movement of rack 213 are only allowed when the pawl 210 is rocked the larger amount by joint operation of rods *c* and *e*.

Another pawl 216 is offset to the side of crank 212 and is also adapted to be operated by rod *e*. 10 This pawl also pivots on shaft 211 and has a forwardly extending arm normally abutting the end of a rack 217 which has a slot guiding it on bar 214 and allowing it to move eight tooth spaces. It is noticed that operation of rod *e* alone will 15 rock both pawls 210 and 216, releasing racks 213 and 217 so that each may move eight steps.

For the purpose of restoring and holding the pawls in normal position, there are provided two rectangular bars 218 to which are fastened leaf 20 springs 219 having extensions bearing upon the pawls.

A bail similar to the one described in connection with the mechanism in Fig. 5 is provided for the purpose of restoring and governing the time 25 of movement of the four racks 203, 209, 213 and 217. This bail consists of two arms 220 fixed to shaft 166, which may be a continuation of shaft 166, Fig. 5, or connected thereto. Two shafts 221 and 222 extend between the arms 220; shaft 30 221 cooperates with racks 213 and 217 and shaft 222 cooperates with racks 203 and 209. Since the operation of this bail is the same as the operation of bail 165, Fig. 5, no further explanation of its operation is thought necessary. 35

Considering the device as far as it is described, it is noted that there are four racks under control of a bank of five rods and that each of the racks has a different extent of movement. One rack 203 can move from one to three steps 40 and the other three racks 209, 217 and 213 are capable of four, eight, and sixteen steps of movement respectively. Operation of the rods *d*, *a*, *b*, *c* and *e* through a perforated card causes one, two, four, eight, and sixteen steps of combined 45 rack movement respectively. It will be noticed that the five rods for controlling these extents of movement are the least number possible for attaining combinations giving 32 different extents of movement. The movement of each rack 50 is a factor of 32 which is the largest number of combinations or different extents of movement possible with five record characteristics in combination.

The devices about to be considered are for the 55 purpose of summing up or adding together the simultaneous movement of any number of the four racks and imparting this movement to a single actuator. These devices are adapted to transmit the movement of a single rack, or 60 movement of any combination of the four racks, to the actuator. In view of the similarity between these devices and those described hereinbefore in connection with Fig. 5, only a brief 65 description is given.

A pinion 223, Fig. 6, meshing with opposite racks 209 and 213, is pivotally mounted by a stud 224 on a rack slide 225. A similar pinion 226 meshing with racks 203 and 217 is similarly mounted on another rack slide 227. These rack 70 slides are held in place and slide on rectangular bars 228 and combs 229 between frames 50 and 51. Rack slide 225 will be moved to the left, one-half the combined movement of racks 209 and 213, namely; zero, two, eight, or ten 75

tooth spaces. Rack slide 227 will move, due to cooperation with racks 203 and 217, zero, one-half, one, one and one-half, four, four and one-half, five, or five and one-half tooth spaces to the left.

Rack slide 227 has a depending arm 230 which is provided with rack teeth opposite to the rack teeth on the end of slide 225. A pinion 231 cooperates with both racks in a manner similar to the cooperation of pinion 223 with racks 209 and 213. This pinion 231 is pivotally mounted on the end of a rack slide 232 which is guided by bar 233 and combs 234. A tension spring 235 between a fixed rod 236 and the end of rack slide 232, urges the slide to the left, Fig. 6. Through the various connections this spring urges the four racks to the left and moves them and the connected actuator when they are released.

From the foregoing explanation it follows that rack slide 232 is moved to the left, one-fourth of the combined distance that the four racks are allowed to move. This movement is one-fourth of, zero to thirty-one tooth spaces, namely; zero to seven and three-fourths tooth spaces on rack slide 232. This movement is multiplied four times and transmitted to an actuator by the following means:

A shaft 237 fixed in the main side frames has loosely mounted thereon a pinion 238 to which is attached a gear 239, the teeth of which are formed on a pitch circle four times the diameter of the pitch circle of the pinion. The gear teeth of pinion 238 mesh with rack teeth 240 on rack slide 232 so that movement of rack slide 232 to the left will rock gear 239 in a clockwise direction. This movement of gear 239 is transmitted to an actuator slide 241 by means of rack teeth 242 on said slide. Thus it is apparent that the actuator 241 receives a movement of zero to thirty-one steps under control of the differential gearing depending upon the combination of rods *a*, *b*, *c*, *d*, and *e*, that is operated. These actuators 241 carry the alphabetic, date, etc., type and have other uses that are described further on in this specification.

In Figs. 7 and 8 are shown views of typical sections through full banks of the jacquard device. In Fig. 7 the dotted outlines enclosing the large numerals 5 represent the spaces occupied by the mechanism shown in Fig. 5, and the dotted outlines enclosing the large numerals 6, Fig. 8, represent the places occupied by the mechanisms shown in Fig. 6. These mechanisms are not shown in detail in Figs. 7 and 8 because the scale would be very small. The views in Figs. 7 and 8 illustrate how, by staggering and properly shaping the mechanisms of Figs. 5 and 6, a very compact and efficient arrangement of a plurality of such mechanisms is obtained. In the plane of one bank of connection rods, devices are confined for operating three actuators. The actuators 187' and 187'', Fig. 7, are operated in a manner similar to the operation of actuator 187 previously described. The positions of the sixteen totalizers in the machine are shown with respect to actuator 187. Additional totalizers could cooperate with 187', 187'', 241, Fig. 8, or 241' if desired. In Fig. 8 two totalizers are illustrated in cooperation with rack teeth on the actuators 241, similarly to Fig. 7. Actuator 241' is operated in a manner similar to the operation of 241. The actuators are shown converged and offset into a common group for printing and controlling. If desired they could be left straight, and

each series of actuators 187, 187', 187'', 241 and 241' could then have individual printing and controlling devices.

Totalizers

In the illustrative embodiment of this invention there are shown sixteen totalizers, one for each of the fifteen agents, and one grand totalizer for registering the totals of the agent totalizers. These totalizers are provided for the purpose of accumulating the amounts taken from a record card and printed upon the bills or receipts which are made in the machine. The totalizer for a certain agent will be selected to receive the amount when the said agent is the one responsible for the taking out of the policy upon which the amount is a premium. The grand totalizer will be selected at the same time that any of the agent totalizers are selected, so that any amount registered in any of the agent totalizers will also be registered in the grand totalizer. In taking totals, however, the totalizers are selected one at a time for operation.

These totalizers are located adjacent the left main side frame 51, Fig. 1B, and above the amount actuating racks 187, Fig. 7. They are arranged in a row, see Fig. 7, with all the totalizer wheels of one denomination in the same plane and adapted for rotation by a common related actuator.

Although only sixteen totalizers are shown in this machine, the totalizers are constructed so that a great many of them may be employed in a machine that would not be much larger than the one illustrated. In such a plural totalizer machine the totalizers instead of being related to an agent could represent a policy holder and register the premiums paid on the policy held.

The novelty of the totalizer construction used has been outlined in the objects stated. It will suffice to state here that the transfer elements for each bank of the simultaneous transferring totalizer disclosed, are composed of parts arranged so that the thickness of one element is all the space needed for each bank; that the motion of the totalizer wheels in going out of mesh is utilized for transferring; and that a large tooth on the totalizer wheel is used for a transfer cam, a total zero stop and a nines coupling lug.

In Fig. 9 is a view showing two totalizers, one totalizer in section with the transfer and registering elements plainly disclosed, and the other totalizer unsectioned with the totalizer engaging and selecting devices shown. Fig. 10 is an end view of a totalizer showing the spacing of the parts. As shown, the transfer elements have embossings pushed out of their thickness of metal so as to separate the parts. This space and embossing is not necessary, the parts may be formed without embossing and moved close together and thus occupy a space equal to but one thickness of metal per bank.

The totalizers are similar to each other in construction, so that a description of one applies to all. Each totalizer is constructed as a removable unit, being held together by two side frames 243 and cross bars 244, 245, and shafts 246, 247. These units are assembled in the machine by inserting the two lower ends of the frame into grooves on shafts 248 and then assembling shaft 249 through the upper notches 250 on the frames. Shafts 248 and 249 are held in the main side frames 50 and 51. Once a totalizer is thus assembled, it is apparent that it is rigidly held in all directions.

5 10 15 20 25 30 35 40 45 50 55 60 65 70 75 80 85 90 95

In Fig. 9 the transfer parts are shown in the position they assume during regular adding operations. The totalizer wheels 251 are loosely mounted on a shaft 252 which passes through slots 253 in the side frames 243 and is secured at its ends to two upright slides 254 and 255. These slides are slotted at 256 to receive studs 257 in the side frames 243. Shaft 252 and slides 254, 255, comprise a frame for carrying the totalizer 5 in and out of mesh with the actuators. Springs 258 are stretched between tabs 259 on the slides and studs 260 in the frames, and tend to engage the totalizer wheels with actuators 187. A cam slide 261 cooperates with a roller 262 on slide 254 10 and normally prevents engagement of the totalizers. However, at the proper time, cam slide 261 is moved to the right, Fig. 9, allowing roller 262 to descend into notch 263 and mesh the totalizer wheels; subsequent movement of cam slide 261 to the left will cam the roller 262 upward and 15 disengage the totalizer. The other slide 255 has an extending lug 13' which overlies a selection bar 265, Figs. 9 and 13, which slides adjacent the totalizers. A notch 312 in bar 265 is normally out 20 of alignment with lug 13' which then is stopped by the upper edge of bar 265, preventing the engagement of the totalizer. However, if the totalizer is selected, bar 265 will be shifted until notch 312 does align with lug 13', thus allowing 25 slides 254 and 255 to be lowered by spring 258 and engage the totalizer when cam slide 261 moves to the right.

The totalizer wheel 251 is made of one piece of metal and has nine of its ten teeth cut off substantially at the pitch line. Cutting the teeth of the wheel in this fashion does not affect its operation because the teeth on the actuator are of the standard height, though they may be tapered above the pitch line. The other tooth 267 on 30 wheel 251 is of full length, and has one side tapered slightly above the pitch line for camming purposes while the other side of the tooth is left practically straight in order to act as a zero stop in taking totals. This tooth 267 in cooperation with a transfer pawl 268 also acts as a nines coupling lug during transferring. The wheel 251 as it is shown in Fig. 9 is in the zero position with the straight side of tooth 267 contacting the under side of the long finger 269 35 on the pawl 268. The pawl 268 also has a short finger 270 for cooperating with tooth 267 in transferring. The pawl 268 has a slot 271 through which passes a shaft 272. Since it is the only mounting, it is about this shaft that the pawl pivots or slides. A leaf spring 273 on 40 bar 244 has an extension for each pawl 268 and presses upon a slanted face 274 on the pawl, thus tending to keep the upper end of slot 271 against shaft 272 and also tending to 45 pivot the pawl counterclockwise about shaft 271 so it will remain in contact with a rod 275. This rod 275 during the adding operation holds the pawls 268 in the position shown in Fig. 9, with the long finger 269 missing the short teeth on 50 wheel 251 but engaging the long tooth 267 above the pitch line, and with the short finger 270 just missing the long tooth 267 during rotation of wheel 251. A small flipper 276 is pivotally mounted alongside the long finger 269 and is of substantially the same width but only as long as finger 270. This flipper is urged in a clockwise direction against the side of the groove in pawl 268 by a small leaf spring 277, and may be rotated in a counterclockwise direction, Fig. 9, but 55 is locked against clockwise movement by the con-

tact of a square side against the vertical side of the groove in pawl 268. The horizontal alignment of the parts on wheels 251 and pawls 268 is well shown in Fig. 12. In this view the higher order wheel is to the left. There it is seen that 5 each of the pawls 268 is positioned between two wheels 251, with the long and short finger of the pawl cooperating with the higher order wheel, while the flipper 276 cooperates with the long tooth of the lower order wheel. Another way of 10 constructing the end of pawl 268 is shown in Figs. 11 and 11a. In the construction shown in these figures, the parts are confined in the space of the width of a single thickness of metal. Flipper 276 does not overlie pawl 268 as flipper 15 276 overlies pawl 268. The flipper 276 extends across the full width of pawl 268' and pivots in a socket 260' in the pawl. A small spring 277' is fixed in the pawl and bears against the top of the flipper. The cooperation of the pawl 268 20 with the wheel 251 will now be described. Pawl 268' is adapted to cooperate with the wheels in a similar manner.

During regular adding operations, the totalizer wheel 251 is rotated in a counterclockwise direction, and in passing from the nine to the zero position, the long tooth 267 passes from above to below the long finger 269, thus camming the finger and rocking the pawl 268 in a clockwise direction. In contact with the upper part of pawl 268 is 30 a plate 278 pivotally mounted on a shaft 246 and offset at 280 so that a projection 281 on the plate is in cooperative relationship with a notch 282 in the higher order pawl 268. When a pawl 268 is rocked by a wheel going from nine to 35 zero, it will rock a related plate 278 so that its projection 281 will be inserted in a notch 282 in the next higher order pawl; thus preventing the pawl 268 from being raised as guided by the slot 271. A detent 283 loosely pivoted on shaft 247, 40 cooperating with notches 284 in plate 278 and held in place by a spring 285, serves to hold the plate 278 in position.

The transfer movement in this totalizer is provided by the movement of the totalizer wheels 45 out of mesh with the actuators. The extent of this movement out of mesh is such that when a pawl 268 is held stationary it will rotate a related totalizer wheel one step. Just prior to the movement of the totalizer wheels out of mesh, 50 the rod 275 is rocked counterclockwise a small extent allowing the pawl 268 to move so that the long finger 269 will engage, not only the long tooth 267 of the totalizer wheel, but all the teeth on the wheel. In this position of the pawls it 55 also will be noted that if a wheel stands at nine, the long tooth 267 will lie between the short and long fingers of one pawl and above the flipper 276 on the next higher order pawl. If the next wheel or plurality of wheels also stand at nine, then 60 they all will be coupled in a similar manner by the fingers and flippers on the pawls. When so coupled, if the pawl 268 of the wheel standing at nine is held latched down by plate 278, then this wheel is going to be rotated by said pawl when 65 the totalizer goes out of mesh with the actuators; and when so rotated, the long tooth 267 thereon will remain almost stationary between the two fingers on the pawl and in this position will overlie the flipper on the next higher order pawl, preventing the pawl from being raised, and causing its long finger to rotate the higher order wheel one step. The same action obtains for a plurality of wheels if a transfer is put in a lower order 70 wheel standing at nine with a plurality of higher 75

order wheels also standing at nine. Each wheel will lock down the higher order pawl by means of tooth 267, and cause a transfer to be entered in all the wheels at nine and the next higher wheel. Thus, it is apparent that a simultaneous transfer is obtained across a totalizer in which the transfer elements of each bank are adapted to be confined in the space of one thickness of the parts comprising the transfer devices.

10 A wheel is given a transfer movement, however, only if its related pawl is locked down by plate 278 or if it is coupled to a locked pawl. If the related pawl of a wheel is unlocked and not coupled it will be lifted up by the disengagement of 5 the wheel which then is not rotated. The slot 271 in the pawl allows it to be lifted, the resistance of spring 273 not being enough to rotate the wheels which at this time are held by detents 286. These detents, one for each wheel, are pivotally mounted on shaft 287 and have a tapered end 288 which allows positive transferring movement of the wheel 251 but prevents movement due to resistance of spring 273 to the lifting of pawl 268. The detent has another arm 289 upon 20 which a leaf spring 290 bears. Also cooperating with arms 289 of detents 286 is a rod 291 mounted between a pair of bell cranks 292 which also carry rod 275. These bell cranks 292 are secured to shaft 272 and form a bail rocking in the bearings 25 for this shaft provided in the side frames 243. The different positions of this bail are shown, Fig. 9, by the phantom circles about rod 291. The bail 292 moves the same way on each operation of the machine, the selection of an adding or 30 total taking cycle being controlled by the time of meshing of the totalizers under control of cam slide 261. The bail is shown in the position assumed during adding or total taking operations, with the pawl 268 in position to be cammed or to 35 act as a total stop as will be described further on, and the detents 286 held out of the path of the teeth on the totalizer wheels. Just prior to the disengagement of the totalizer with the actuator, the bail is rocked slightly counterclockwise allowing 40 the pawl 268 to engage the short teeth on the totalizer wheel and permitting detent 286 to engage the teeth on the wheel. At the beginning of the next operation of the machine, the bail is rocked clockwise so as to fully disengage the 45 pawls 268 from the totalizer wheels allowing them to move freely into mesh if a total is to be taken. The actuator 187 moves first to the left and then to the right, Fig. 9, during an operation of the machine, so that if a total is to be 50 taken, the totalizer wheels are meshed before the first movement of the actuator, and the bail is timed accordingly. After the totalizer is in mesh, the bail again assumes the position as shown in Fig. 9 wherein pawls 268 may act as a total stop. 55 The pawls 268 are locked from being raised as a total is being taken because on the previous clockwise movement of the bail, all the plates 278 were rocked so projections 281 engaged notches 282 in the pawls. The wheel is rotated in a clockwise 60 direction during total taking until the flat face of the long tooth 267 abuts against the finger 269 of the pawl which acts as a total zero stop, the wheel having rotated an extent equivalent to the amount previously standing thereon. Then 65 the bail is rocked clockwise so that the pawls will be free of the teeth of the wheels as they go out of mesh after taking a total. At this time no transfers are to be entered into the wheels, for either they have remained out of mesh with the 70 actuators during the early part of an adding cycle 75

or have been rotated in taking a total. If an adding operation is required, the totalizers will be meshed with the actuators at this point in the operation, after which the bail is rocked counterclockwise to such an extent that rod 291 will cam extensions 293 on plates 278 so as to withdraw the projections 281 from notches 282 and restore the plates to normal position. Before the actuators move to the right, Fig. 9, and rotate the totalizer wheels in a counterclockwise direction 10 for adding, the bail is again rocked into the position shown on Fig. 9. The means for rocking the bail will now be described.

Attached to the end of shaft 272 (Figs. 9 and 15 10) is an arm 294 to which is pivotally connected a link 295. This link is connected in the same way with the arms 294 of all the other totalizers, see Fig. 1B. In that view it is also seen that the link 295 has a connection to the end of an arm 296 that is inside frame 50 and is mounted 20 on a shaft 297 which connects it with another arm 298 on the outside of frame 50. A link 299 connects arm 298 with one end of a bell crank 300 pivoted in the side frame and having a roller on its other end cooperating with a box cam 25 groove 301 in the gear 65. It is apparent that the rocking of bell crank 300, by the proper convolutions of the cam, will be transmitted through link 299, arms 298 and 296, link 295, and arms 294 to the bails 292 to give them the motions 30 mentioned above.

Totalizer selection

During the item entering operation of the machine, two totalizers are selected automatically 35 for engagement with the actuators; one is the particular totalizer for the agent associated with the item being recorded; and the other is a grand totalizer that is always engaged. Prior to a total taking operation of the machine, a single totalizer 40 is selected by a manipulative lever which upon movement, prevents engagement of all but one totalizer. A novel feature of this selection device is the use of a common selection bar for both 45 automatic and manipulative selection.

Behind a shoulder 302 cut in the agent's actuator 187, Fig. 13, is a lever 303 which is connected to the actuator by a spring 304 so that a stud 305 on the lever remains in contact with the actuator and positions the lever in accordance 50 with the extent of movement of the actuator. This lever 303 is pivoted on a stud 306 in the frame 51, and at its other end contains a stud 307 against which the selection bar 265 is held by a spring 308 connected to the bar. The actuator 187 is moved differentially by the devices 55 described hereinbefore with reference to Figs. 5 and 7. From the above connections it is apparent that movement of the agent's actuator to the right will yieldingly position the selection bar 60 a differential extent to the left, and restoration of the actuator to the left will yieldingly restore the bar to the position shown in Fig. 13.

The selection bar 265 slides on studs 309 in the side frame and is provided with notches 310, 65 311, etc., similar to the notch 312 shown in Fig. 9. Overlying the top of bar 265 and cooperating with the notches are lugs 1' to 15' and GT', each of which is integral with a related totalizer engaging slide 255, as is the lug 13' of Fig. 9. Only five 70 of the lugs are shown in Fig. 13 where the selection bar is broken, but it is understood that there are sixteen such lugs cooperating with the notches in the bar.

In the right end of the bar 265 is a large notch 75

315 which is cut from one step to the right of lug GT' all the way over to projection 316. So, it is apparent that movement of bar 265 to the left, any of the fifteen extents possible, will select the grand totalizer for an adding operation. The other small notches are arranged on the bar at differentially stepped distances from the lugs so that to align lug 15' and notch 314, one step of movement of bar 265 to the left is necessary, to 5 align lug 14' and notch 313 two steps are required, etc.; when the totalizer associated with lug 1' is to be selected, notch 311 must be moved fifteen steps to align with lug 1'. The notch 310 one step to the left of lug 1' is not used in 10 adding selection but will be accounted for herein-after.

The above devices are provided for automatic totalizer selection during adding operations. Now the means for manually selecting a totalizer 15 for a total taking operation will be discussed.

Fastened to the case 53, Fig. 13, is a frame 317 carrying an overturned semi-circular shoulder 318 which has a slot 319 provided with locating notches 320. There are 17 such notches, one for 20 each totalizer and one for holding a lever 321 in an inoperative position. This lever 321 is pivotally mounted at 322 in frame 51 and has an upwardly extending arm carrying a locating projection 323 and a knob 324. This lever may be 25 rocked in slot 319 and the projection 323 located in any notch 320. A lower arm of lever 321 carries a pin 325 which is normally out of the path of projection 316 on bar 265. However, if the lever is rocked to coincide with the first notch 320, 30 pin 325 will move bar 265 one step to the right, and notch 310 on the bar will align with lug 1', thus selecting the totalizer related to lug 1' for a total taking operation. It will be noted that 35 all the other totalizer lugs, including the grand totalizer lug, will be locked by bar 265 at this time.

If the lever 321 is rocked to the second notch 320, bar 265 will be moved two steps to the right and notch 311 on the bar will align with lug 2', thus selecting the related totalizer. It will be remembered that this same notch 311 is used to 40 select the totalizer related to lug 1' for adding operations. The reason it is possible to use a common notch for selecting one totalizer for adding 45 and another for total taking is because there is a space equal to seventeen steps of selector bar movement between lugs, and the notches are placed differentially between the lugs with the distance to one of the lugs being complementary 50 to the distance to the other. In this way, notch 313 is two steps from lug 14' and fifteen steps from lug 15'. In a similar manner, notch 314 is one step from lug 15' and sixteen steps from lug GT'. From the foregoing it is clear that 55 a common bar 265 and the notches 311, etc., in the bar, may be used for both automatic adding selection and manual total taking selection.

A downward extension 326 on bar 265 cooperates with a pin 327 on the end of a lever 328 pivoted at 329 on side frame 51. During adding 60 selections, when bar 265 is moved to the left, lever 328 is not moved. However, upon total taking selections, when bar 265 is moved to the right, then lever 328 will be rocked clockwise an amount indicative of the totalizer selected. A 65 depending arm of lever 328 has a stud 330 in contact with the rear end of a special type bar 331. A spring 332, between the type bar and frame 51, restores the type bar and lever 328 to a position against stop stud 333. The type 70

on this type bar 331 are provided to print a special sign indicating that a total has been taken and a number indicating the totalizer selected, see printed item 334, Fig. 21.

Totalizer engagement

5

The totalizers, after being conditioned for engagement by the selection device, are engaged with the actuators by mechanism which governs the period of engagement with the actuators. 10 This period of engagement may be altered by manipulative means so that a total, sub-total, or non-add operation will occur instead of an ordinary adding operation. In addition to the manipulative keys for securing a total, sub-total, 15 or non-add operation, there is also provided a control key for placing the period of engagement of the totalizers under the control of a control mechanism. This phase of totalizer engagement will only be partially described under the above 20 heading but will be completely discussed under the heading of "Control mechanism."

The totalizer engagement has already been discussed with reference to Fig. 9 wherein a cam slide 261 cooperates with a roller 262 on slide 254 25 and normally prevents engagement of the totalizer. However, at the proper time, cam slide 261 is moved to the right, allowing roller 262 to descend into notch 263 and shaft 252 to lower to mesh the totalizer wheels with the actuators. Re- 30 ferring to Fig. 1B, it is seen that slide 261 cooperates with the rollers 262 for all the totalizers and they are controlled by a common actuating device.

The slide 261 is provided with slots for sliding 35 on studs 335 extending from side frame 50, see Figs. 1A and 1B, and is frictionally held in place by the pressure of rollers 262 upon it. An arm 336 on the inside of frame 50 is mounted on a shaft 337 and has a pin and slot connection with 40 the slide 261. The shaft 337 extends through a bearing in frame 50 and has secured to its end, outside the frame, an arm 338 which has a pin and slot connection with a slide 339 mounted on the frame. From the above connections it is 45 apparent that the sliding movement of slide 339 will be transmitted to cam slide 261.

The slide 339 has two extensions 340 and 341 upon which studs, in the arms of four operating cranks 342, 343, 344, and 345, act to push the 50 slide back and forth. These cranks are operated by a pin 346 extending from the outside of gear 351 and a pin 347 extending from the inside of gear 351. This gear 351 is similar to gear 62 but is not connected therewith but is driven in a reverse direction by a pinion 352 which is in mesh with gear 63. The crank 343 is pivoted on a fixed stud in the side frame 50. The crank 342 is pivoted on one end of a lever 348 mounted on a stud 349 in frame 50, while crank 345 is pivoted on 60 the other end of this same lever. Crank 344 is pivoted on an arm 350 also mounted on stud 349 in the side frame. Springs and stop studs on the frame 50 keep lever 348 and arm 350 in normal position. 65

For normal adding operations the cranks will be positioned as shown in Fig. 1B, with crank 345 lowered for operation with crank 343; while cranks 342 and 344 are raised out of the path of the pins 346, 347. Upon operation of the machine, gear 351 is rotated counter-clockwise and pin 347 in the gear approaches crank 345. After the actuators 187, Fig. 7, have been given their initial movement to the right, pin 347 strikes the cam face of crank 345 and rocks it counter-clock- 70 75

wise about its pivot on lever 348; the stud in the upward extending arm of the crank then pushes slide 339 to the left. This movement of slide 339 to the left is transmitted to cam slide 281 which then allows the selected totalizers to go into mesh with the actuators. The totalizers remain in mesh until near the end of the operation of the machine, when pin 346 in gear 351 cams crank 343 rocking it in a clockwise direction and, by means of a stud in the vertical arm of the crank, pushes slide 339 to the right, thereby disengaging the totalizers from the actuators.

To secure non-add operations, during which none of the totalizers is meshed with the actuators, a key 353 is depressed and latched to the cover 53. The end of key 353 cooperates with the right arm, Fig. 1B, of lever 348, and when depressed rocks this lever about stud 349, lifting crank 345 out of the path of pin 347. Both cranks 342 and 343 will then be in the path of the pins, but they will be rocked idly because slide 339 is already located in a position to the right where it remains throughout the non-add operation, holding the totalizers disengaged.

25 To secure a sub-total taking operation, during which it is desired that the totalizer remain in mesh with the actuators throughout their reciprocating movement, a key 354 is depressed and latched to the cover 53. The end of key 354 abuts against the arm 350 and when depressed rocks this arm so that crank 344 is lowered into the path of pin 346. Depression of arm 350 also rocks arm 355 which is connected to shaft 149, Fig. 5, clockwise, thus unlocking the actuators 187 so 30 that they may be moved freely in total taking.

Early in the operation of the machine, pin 346 cams crank 344, rocking it in a counter-clockwise direction, thus shifting slide 339 to the left and engaging a totalizer with the actuators. The totalizer will remain engaged until near the end of the operation of the machine when pin 346 rocks crank 343 which pushes slide 339 to the right, disengaging the totalizer.

45 To secure a total taking operation, during which it is desired that a totalizer be engaged with the actuators during their initial movement but be disengaged before the final movement, a key 356 is depressed and latched to the cover 53. A pin 357 in an extension on key 356 overlies arm 350, so that when key 356 is depressed, arm 350 will be rocked as in sub-totals, lowering crank 344 into the path of pin 346, and rocking arm 355. A shoulder on key 356 abuts against one arm of 50 a lever 358 which is pivoted on the side frame 50. The other arm of this lever 358, contacts a projection on lever 348, so that when key 356 is depressed and lever 358 is rocked, lever 348 will also be rocked in a clockwise direction, lifting crank 345 out of the path of pin 347 and lowering crank 342 into its path.

60 Early in the operation of the machine, pin 346 cams crank 344, rocking it counterclockwise, thus shifting slide 339 to the left and engaging the totalizer with the actuators. The totalizer will remain engaged during the forward movement of the actuators, but soon after, pin 347 rocks crank 342 which then shifts slide 339 to the right disengaging the totalizer before the return movement of the actuators.

70 The slide 339 is under other control for engaging and disengaging the totalizers. The connections for this control will be described further on 75 in the specification.

Printing devices

The data compiled by the machine of the present invention are printed upon a record strip and an issued bill or receipt. The matter printed upon the record media is not all presented on a single line, but it is arranged on two lines, and the groups of related printing are alternated first on the upper then on the lower line across the sheet, see Fig. 20. This style of printing from a single group of type bars is especially effective in printing an address directly beneath a name in the form for mailing.

In general, the printing mechanism comprises a type member pivotally mounted on the actuator and cammed to and from printing position by means of eccentrics on a shaft that extends through slots in the actuators and type members. During the rotation of the eccentric shaft the platens for the type are raised and lowered in time to properly receive the impressions of the type carriers which are interspersed and arranged to print two lines of data upon a single operation of the machine. The driving connection may be disabled for a no print operation.

It is mentioned hereinbefore with reference to Figs. 7 and 8 that the actuators converge and are offset to form a single line of slides at the front of the machine. The grouping of all the actuators in a single line is clearly observed in Fig. 23 where it is seen that the actuators 187, 241, etc., are adjacent each other and each has a slot 359, Fig. 14, by means of which a bar 360 and a comb 361 guide the movement of the actuators. In Fig. 14 it may also be noted that pivoted on a pin 362 on each of the actuators is a type carrier 363 provided with an upper set of type 364 and a lower set 365. The type may be numerical, date, or alphabetical, depending upon which actuator they are associated with. The sets of type overhang the actuators so as to substantially fill the space between the type, see Fig. 16. There is clearance enough, however, between the overhanging type and the top and bottom of the actuator, to allow the type carrier 363 to be rocked up or down, impressing the type against platens 366, 367, 368, and 369. Certain of the type carriers 363, such as the number, amount, date, and name type carriers, cooperate with platens 367 and 369, and print above (see Fig. 20) the impressions from the age, agent, policy number and address type carriers which cooperate with platens 366 and 368. Each of the platens is held in a frame 370, Fig. 17, which is secured to two sliding blocks 371 that slide in slots 372 in the main side frames 50 and 51 or on brackets secured thereto. A compression spring 373 between the side frames and the platen frames, tends to move the platens into printing position. As the type carriers 363, Fig. 14, are rocked up or down, the platens 366, etc., are raised or lowered so that printing will not occur simultaneously at two lines on a sheet by impressions from the same set of type. The means for rocking the type carriers, and raising or lowering the platens, comprises eccentrics 374 mounted on a square shaft 375. The means for rotating this shaft 375 will now be described.

Referring to Fig. 1A it is seen that disk 73 is provided with a segmental group of teeth 74 which, when the disk is rotated by the main operating mechanism, give the gear 376 a complete counter-clockwise rotation. This gear 376 is mounted on a stud on side frame 50 and is in mesh with a gear 377 loosely mounted on a shaft 75

378 which extends through the side frames. Another gear 379, Fig. 14, alongside of gear 377 but not in mesh with gear 376, is fastened to shaft 378 and is adapted to turn the shaft when it is coupled to gear 377 by a broad faced pinion 380. Normally this pinion 380 couples the two gears, permitting a printing operation. It may be disengaged at times, under control to be described further on in the specification, so as to cause a nonprint operation.

Fastened to the shaft 378, inside each of the main frames, is a pair of gears 381, Fig. 14, in mesh with a pair of gears 382 secured to shaft 375. From the above connections it is apparent that square shaft 375 will normally be given one complete counter-clockwise rotation upon each operation of the machine.

The eccentrics 374, Fig. 14, operate in slots 383 in type carriers 368 and are held in position by virtue of the shoulder of a slot 384 in the actuators; the slot is purposely made narrower than slot 383 so as to confine the eccentrics. Two pairs of eccentrics 374 are devoted to raising and lowering the platens, Fig. 17. One pair 25 of eccentrics cooperates with two plates 385 (one on each side of the machine) for raising and lowering platens 367 and 369, while the other pair cooperates with plates 386 which raise and lower platens 366 and 368. These plates 385 and 386 have slots 387 and 388 for sliding upon studs 389 in the side frames 50 and 51.

Normally the shaft 375 holds the eccentrics 374 so that their eccentricity lies in a horizontal line through the center of the shaft, Fig. 14. One set of eccentrics for the number, amount, operator, date, and name type carriers have their eccentricity to the right side of shaft 375 while the other eccentrics for the age, agent, occupation, policy number, and address type carriers 40 have the eccentricity to the left of shaft 375 as seen in Fig. 14. The pair of eccentrics for plates 385 are oppositely arranged to those for plates 386. Thus, it is apparent that normally all the type carriers 363 are in a central position. They 45 are held so during the adjustment of the actuators, after which, at the proper time, shaft 375 is rotated.

After 90° of rotation of shaft 375, Fig. 16, the eccentrics will have raised the type carriers including the address type forming the lower line in Fig. 20, and have lowered the type carriers including the name type forming the upper line in that figure. Meanwhile, the eccentrics 374 and plates 385, 386, Fig. 17, have raised platen 367 55 and lowered platen 368 out of cooperation with the type. So that at this point in the operation of printing, an impression including the address is taken from the upper type 364 of the raised type carriers which then cooperate with platen 366, while an impression including the name is taken from the lower set of type 365 on the lowered type carriers which then cooperate with platen 369. The typebars carrying the name type are interspersed between the typebars carrying the address type. The reason the platens 60 are raised or lowered out of cooperation with the type is to prevent the name type from printing on line with the address and vice versa.

The shaft 375 is rotated further until at 270° 70 of rotation the type carriers and the platens will assume a position just the reverse of their position at the 90° point. At this point the eccentrics have lowered the type carriers including the address type and have raised the type carriers 75 including the name type. Meanwhile plates 385

and 386 have raised platen 366 and lowered platen 368 out of cooperation with the type, leaving platens 367 and 369 in impressing position. So that at this time an impression including the name is taken from the upper type 364 of the raised type carriers which cooperate with platen 367, while an impression including the address is taken from the lower set of type 365 on the lowered type carriers which then cooperate with platen 368. The completion of the rotation of shaft 375 adjusts all the type carriers to a central position, after which the actuators are returned to normal position.

From the above description it is believed clear that during printing, a group of interspersed type carriers, in groups as the amount type, see Fig. 20, or singly as name type, will print an upper line of data on two record media, while another group of type carriers interspersed between the above mentioned type carriers and arranged in groups, as age, type, or singly, as address type, will print a lower line of data on the said record media. The record media provided for receiving the printing impressions will now be described.

A roll 390 (Fig. 14) of paper is loosely mounted on a shaft 391 between frames 50 and 51. The paper 390' from the roll is fed, by means of roller 392 and electro 393, between knife blades 394 and 395, and between inking ribbons and the platens 368, 369. After the paper is printed upon by the lower set of type 365 it is severed by movement of knife blade 395 and is allowed to pass out of the machine through a chute having walls 396. The end of knife blade 395 extends through side frame 50 and is connected by a link to a lever 397, Fig. 1A, which is rocked on each operation of the machine by a pin 398 in disk 73. A sample of such an issued bill is shown in Fig. 22. There it is noted that a bill form has been printed by the electro, while the name, address, amount due, etc., has been printed from the type carriers in the machine. On such a bill it is not necessary to print all the information shown on the statistical sheet in Fig. 20, so the lower type are left off certain of the type carriers. It will also be noted in Fig. 22 that part of the address, Oakdale L. L., is lowered on another line below that of the street name, thus forming three lines of print for the name and address. The address may be printed in such a manner by offsetting a portion of the platen 368 and arranging the type on the type carrier accordingly.

The supply roll 399, Fig. 14, of record paper 400 is loosely mounted on a shaft 401 held in frames 50 and 51. This record strip 400 passes between guide rollers 402, 403, between the platens 366, 367, and the inking ribbons, through the guide rollers 404, 405, on to a storage roll 406 which is secured to a shaft 407 adapted to rotate in the side frames 50 and 51. The roll 406 is made accessible for removal by a cover plate 54 which is hinged to the case 53. Examples of printed record strips are shown in Figs. 20 and 21. Fig. 20 shows a record having printed thereon all the data provided in the illustrative machine; such a record may well be used for statistical work. Fig. 21 shows a record in the form of a detail strip having one printed item, leaving out certain data, and a printed total with the special sign 334 and the related amount printed on the same line.

The pairs of inking ribbons shown may be fed by any ribbon feeding device, many examples of which may be found in the prior art.

The devices for feeding the record media are

- shown in Fig. 1A. The disk 75 is provided with two sets of gear teeth 76 which cooperate with a gear 408 that is loosely mounted on a shaft 409 which has secured thereto the slip feeding roller 392, see Fig. 14. Operation of the machine and rotation of disk 75 will cause the two sets of teeth thereon to rotate gear 408 two revolutions in a counter-clockwise direction. Adjacent gear 408, and of a similar size, is another gear (not shown) which is secured to shaft 409. A broad toothed pinion 410 serves to couple the two gears on shaft 409 when paper feeding is desired. This pinion 410 is connected by lever 411 and link 412 to the print disabling pinion 380, previously mentioned, for movement in synchronism. Lever 411 is pivoted on a stud in the side frame 50. From the above connections it is clear that printing and paper feeding are enabled or disabled simultaneously.
- 20 When the pinion 410 couples the two gears on shaft 409; roller 392, Fig. 14, upon operation of the machine, will feed the paper strip 390. A sprocket (not shown) is also fixed on shaft 409 outside the frame 50. Around this sprocket is wrapped a chain 413, Fig. 1A, which transmits the movement of shaft 409 to a gear sprocket 414 loosely mounted on a stud 415 in side frame 50. Secured to the sprocket 414 is a gear 416 which is in mesh with a gear 417 fastened to the end of shaft 407, Fig. 14, hereinbefore noted as the shaft carrying the record storage roll 406. From the above description it is obvious that slip 390' and record strip 400 are fed from supply rolls 390 and 399 simultaneously, and that if slip feeding is disabled, the record strip feeding also is disabled.

Control mechanism

The machine of this invention is provided with control mechanism for controlling the operation of many functions in the machine according to the comparison of certain data set to control, and the data presented in the machine by the punched cards and extents of movement of the actuators. By data are meant any name, number, date, address, etc., such as the information printed on the statistical sheet shown in Fig. 20. A certain name, number, or date, or a range of such data, may be set up by the operator of the machine, and then upon operation of the machine, those data are automatically compared with the name, number, date, etc., tendered to the machine and converted into movement of the actuators to different extents. The range of control may be set by the operator to be above, below, or between the certain names, numbers, or dates set up; or it may be set so as to control when the data presented by the machine are exactly the same as the data set up. The terms "range of data", and "above, below or between data" mean the position of names, dates, or numbers in the alphabetic, dating, or numerical scales and may be best illustrated by an example. Taking the name "Smith" for example, the range of data above this name in the alphabetic scale begins with Sn and continues throughout all the names beginning with T, U, V, W, X, Y, and Z; the range of data below "Smith" in the alphabetic scale begins with Aa and continues through B, C, D, etc., up to Sl. The range of data between the names "Brown" and "Smith" includes all the names beginning with the letters Bs—C, D, E, etc., up to the letters Sl.

To secure "between index" control over a range of names between two selected names comprising a plurality of letters, the machine may contain

two banks devoted to name set-up knobs. The paired knobs of one bank may be set between the lowest letters in the scale and the letters spelling the one selected name lowest in the alphabet as, for example,—AAAAA and Brown. The knobs in the other bank may be set to the highest letters in the scale and the other selected name highest in the alphabet as,—ZZZZZ and Smith. The name data presented to the machine would then be compared with the name set-ups in both banks, and the sorting, printing, accumulating, etc., control would be effected or disabled according to whether or not the name data fell within the range of control selected.

During the operation of the machine, comparison of the data set up with the data presented by the machine takes place; and if they are enabled, the control devices then are adapted to change many of the functions of the machine as the machine operates. The devices for meshing the totalizers for adding may be disabled so that a no add operation results. The printing devices are disabled so that a no print operation occurs. The sorting devices are actuated so that the cards containing data that exert control are sorted from the cards not having data that cause the control mechanism to function. The paper feeding devices are disabled, preventing the feeding of the record strip and the issuing of a bill. During total taking operations, the totalizer engaging mechanism may be so controlled as to change the function to a subtotal taking operation; and during sub-total taking operations, the totalizer engaging mechanism may be so actuated by the control devices that a total taking operation re-

5

35

The control of the control mechanism over the totalizers during adding, total taking or sub-total taking is optional and is put into effect, only upon the depression of an accumulator control key provided in the machine.

In general, the control mechanism comprises settable control knobs which may be positioned to form a name, number, or date. Each knob has slidably attached thereto a finger which is held depressed in contact with the upper edge of a related actuator. This upper edge of the actuator is cut to form three different levels to which the finger may fall as the actuator is moved. The high level maintains a set finger in raised position indicating that the actuator has not moved an extent equal to or above the data set up. The lower level allows the finger to descend a step indicating that the actuator has moved an extent forming data above the data set up. The lowest level or notch in the top of the actuator, when it coincides with a related finger, allows the finger to descend two steps, indicating that the actuator has been moved to a position in the alphabetic, date or numerical scale, that is exactly the same as the position to which the finger had been set by the operator.

The above paragraph describes generally the portion of the control devices for sensing and comparing the data set up with the data tendered in the machine by the punched cards or actuator movement under control of a totalizer when taking a total. In addition, the control devices comprise a control lever which sets devices to determine the range of control desired. The ranges possible are above, below, or between the data set up, or exactly the data set up.

After the control lever is set for the range and the control knobs are positioned to form the set up data, the machine is operated. First, the fin-

gers sense and compare the data tendered by the machine with the data set up; then devices under control of the fingers are actuated according to whether the data tendered by the machine are in the control range or not. If the data are in the control range, the control devices are actuated and they then cause no-printing, no-adding, sorting, etc.

A detailed description of the control devices follows, reference being made to the drawings in the application.

Reaching across the machine above the front of the actuators and secured to the side frames is a control plate 418, Figs. 14, 23, and 24, which is provided with notched slots 419 in which control knobs 420 are set to form a name, number, date, etc. The plate 418 has a slot for each of the number, age, amount, agent, operator, occupation, date, policy number, city, and state designating actuators, and two slots located above the first two actuators carrying the name type. Each slot in the plate has a plurality of notches which are equal in number to the positions of the actuator with which the slot is related. For example, the date months slot has twelve notches, one for each month.

The knob 420 is flexibly held on a guide plate 421, Fig. 14, the lower end of which is bent to form a socket 422 in which slides vertically a finger plate 423. Each of the guide plates 421, as seen in Fig. 23, has a horizontal portion underlying the related slot in plate 418 and an offset portion which terminates in a socket 422 that is poised over a related actuator so that the sliding finger 423 may cooperate therewith. A pair of studs 424 on plate 421 hold it against plate 418 and guide it in movement along the slot 419. The control knob 420 has a shoulder that is the same diameter as the notches in the slots, and is held down, with the shoulder in the notch, by a compression spring in the knob, that presses between a stud on plate 421 and a ledge inside the knob. This construction inside control knob 420 is not shown as it is an old expedient. The knob may therefore be lifted out of any notch, be moved along the slot with plate 421 and dropped into another notch; thus positioning plate 421 and finger 423. From the foregoing it is clear that the fingers 423 are guided in their vertical movement and may be positioned to a number of positions that coincide with the different extents of movement of a related actuator.

The beveled point of the fingers 423, Fig. 14, normally rests on the shelf of a slotted guide plate 425. Instead of a beveled point on the finger, a roller could be mounted on the end of the finger to cooperate with the cam faces on the top of the actuator. When a finger is moved out of normal position, a slot 426 in plate 425 guides its lower end and holds it in contact with the top of a related actuator. The guide 425 reaches across the interior of the machine and is secured to frames 50 and 51.

Each finger 423 is provided with a pin 427 which projects into a long slot 428 in a link 429 that is suspended between a pair of arms 430 loosely pivoted on shafts 431 between the side frames. The arms 430 are equal in length and hold the link 429 horizontal in all raised and lowered positions. The slot 428 is long enough to allow finger 423 to assume any of its adjusted positions. The ends of plate 425 guide the link 429. By means of this link and arm construction any downward movement of finger 423 in any

of its positions will be transmitted into counter-clockwise rotation of arms 430. A spring 432 connected to each rear arm 430 normally holds the parts depressed with finger 423 seeking a lower level.

The top surface of the actuators, upon which the beveled point of finger 423 bears, is cut to form three different vertical levels, a high level 433, Fig. 15, a lower level 434, and a notch 435. The notch in the actuators is so positioned normally that if the knob 420 is brought to the O position on plate 418, finger 423 will fall into the notch. So also if a finger is moved to the M position and the related actuator moves to an extent required to print M, the finger will fall into the notch. In other words, the notch 435 in each position of the actuator has an exact relative position along a slot 419, and when this relative position is occupied by knob 420, the associated finger 423 will drop into the notch.

The finger 423 may be adjusted to a position above or higher in the scale than that represented by the movement of the actuator. In such a case the finger 423 will remain perched upon high level 433. One example of this would be presented when an amount finger is positioned at 8 and the actuator only moves to print 6 or 7; the finger then would remain raised. Again, if a date finger is set at June and the actuator only moved to May; or a name finger stood at P and the actuator only moved to O, the same condition would be obtained.

The finger 423 could also be set in a position below or lower than that represented by the movement of the actuator. In such a case, the finger 423 would drop one step to level 434, half way between the vertical position assumed when on level 433 or in notch 435. An example of this would be presented when an amount finger is positioned at 8 and the actuator moves to an extent adapting it to print 9, the finger then would be lowered one step. For other examples; if a date finger stood at June and the actuator moved to July, or a name finger stood at P and the actuator moved beyond to Q, similar conditions would be obtained. The springs 432 urging the fingers 423 downward will cause them to assume the level presented by the actuator.

From the above three paragraphs it is clear that an adjusted finger and its connections will have one of three different vertical positions after the movement of a related actuator. The raised or highest vertical position of the finger shows that it has been adjusted, in its scale, above the character presented for printing by the positioned actuator. A lower vertical position of the finger shows that it has been adjusted below the character presented by the positioned actuator. And the lowest position of the finger shows that it has been adjusted to a character in its scale that is exactly the same as the character presented by the shifted actuator. Thus, a sort of comparison is made between the data set up with knobs 420 by the operator of the machine, and the data tendered to the machine by movement of the actuators. It is apparent that the front arm 430 will have three angular positions corresponding to the three vertical positions of the finger. The one position will be that shown in Fig. 14, and in the other two positions the arm 70 will be rocked slightly in a counter-clockwise direction.

In Fig. 15 is shown another form of control which is adapted to set controls at two points in a scale and, in the range between the two points, 75

exercise control over the data presented to the machine. Two fingers 436 and 437 cooperate with a single actuator. Each of the fingers is mounted in a plate 421 with a knob 420 that can be positioned along a common slot 419. Pivoted in a socket on the side of each of the fingers are the ends of a link 438 which carries a pin 439. This pin protrudes into the slot 428 cut in link 429 and raises this link and its connections in a manner somewhat similar to the action of pin 427 in Fig. 14. The pin 427, however, only has three vertical positions while pin 439 has a few more as will be described farther along in this description.

The two knobs 420 associated with fingers 436 and 437 are positioned in two notches along slot 419. For example, if finger 436 is positioned at M in an alphabetic slot, then finger 437 may be positioned at H. If it is desired to increase the range to between G and N, a longer link 438 may be used or the link could have a pin and slot connection to the fingers instead of the socket connection shown, thereby giving the fingers an adjustable range, see Fig. 15A.

When the actuator is moved, the pin 439 will assume one of a few vertical positions, the location depending upon the positioning of fingers 436 and 437 by upper edges 433, 434, and 435 on the actuators. The positions of pin 439 will be discussed in the order that the pin descends vertically. It will be assumed that finger 437 stands at 3 and finger 436 at 8, in the date scale they could stand at March and August. In the first or highest position of pin 439 both fingers 436 and 437 will be supported on level 433, showing that the actuator has moved less than three steps. In the second position finger 437 will contact level 434 and finger 436 will be supported on level 433, as shown in Fig. 15, indicating that the actuator has moved between three and eight steps. In the third position of pin 439, finger 437 will be in notch 435 due to the movement of the actuator to 3. In the fourth position both fingers will rest on level 434, showing that the actuator has moved a greater extent than eight steps. In the fifth position, finger 436 will drop into notch 435 indicating that the actuator has moved eight steps.

To avoid repeating the description of certain portions of the control devices in pointing out the condition of the controls when the mechanism shown in Fig. 15 is employed, a comparison will be made at this point between the devices in Fig. 14 and those in Fig. 15. The first position of pin 439 corresponds to the highest position of pin 427; the second and third positions of pin 439 correspond to the middle vertical position of pin 427; and the fourth and fifth positions of pin 439 correspond to the lowest position of pin 427. With this similarity in mind it is to be understood that the control to be described further on, due to the vertical position of pin 427, applies as well to the devices including pin 439. When the devices in Fig. 15 are used it is clear that it would be futile to move lever 440 (to be described further on) to "exact index control" position. It is contemplated that a "between index control" position of the lever be provided coinciding with the "above index control" position, and that the lever in this position will act in a manner similar to the control described hereinafter with reference to the lever in "above index control" position.

Abutting the end of each front arm 430, Fig. 14, is a plate 441 pivoted on a stud 442 in the end of an arm 443. The plate 441 is held in contact with the end of arm 430 by a spring 444, so that

when arm 430 assumes one of its three positions, plate 441 will rock on stud 442 and also assume one of three positions. There is a plate 441 cooperating with each arm 430 and the plates are arranged in groups corresponding to the groups of actuators and control devices, namely, a number group, an age group, an amount group, etc. Each plate 441 has an offset lug 445 which projects over a similar lug on the lower order plate, the arrangement being such that even if the lower order plate tends to follow the rocking of its arm 430 it cannot do so if the higher order plate is held to the left, Fig. 14, by its arm 430.

The arms 443, upon which the plates pivot, are loosely mounted on a fixed shaft 446 that extends between the main side frames; and they are urged in a clockwise direction by springs 447. In the normal position, the arms 443 are in a horizontal position and in contact with the top of a stop rod.

The bottom of each plate 441 has a downward extension 448 projecting from a point in the center of two cut out portions on the plate. The end of the extension 448 is notched and in certain positions of plate 441 the extension is engaged by the cross beam of a lifting bail 449 provided for lifting plates 441. This bail 449 cooperates with all the plates 441 and has a forwardly extending arm on each side of its cross beam, which arms are slotted and held by headed studs to the side of arms 450 which are fixed to a rock shaft 451 that raises and lowers the bail. Springs between arms 450 and bail arms 449 hold the bail normally forward with the rear stud contacting the end of the slot in bail arm 449.

The means for rocking the shaft 451 and bail 449 is shown in Fig. 1A. A disk cam 72 driven by the main operating mechanism actuates a bell crank 452 which is connected by a link 453 to an arm 454 that is fixed on the end of shaft 451. At the proper time the cam 72, striking a roll 455 on the end of the crank arm, rocks the crank counter-clockwise about stud 456 in the frame 50 and shifts the link 453 to the right, thereby rocking the shaft 451 and bail 449 in a counter-clockwise direction. A spring 457 between a stud in the frame and crank 452 holds the roller 455 against the cam 72 and restores the bail 449 and its connections to normal position.

Cooperating with each group of plates 441 is a stud 458 that lies above the lower forward projection on the plates. The contour of the surface of the plate in cooperation with stud 458 is an arc about stud 442 as a center so that the vertical position of stud 458 will not change as plate 441 is rocked about its center. However, if any of the plates in the group are lifted by bail 449, stud 458 will transmit the motion to a link 459 in which it is mounted. It is clear that there is provided a link 459 for each group of plates 441, 60 which link receives the vertical movement of any one of the plates in the group.

The links 459 are guided on their upper ends by slots in a bar between the main frames and guided in the lower portion by having slots 460 through which a rod 461 extends between the side frames.

The extreme lower end of each link 459 carries a pin 462 over which lies the front end of a large control plate 463, (one for each link, see Fig. 23), 70 that is pivoted on stud 464 in the end of arm 465. A spring 466 holds each control plate 463 in contact with a pin 462. Upon raising of link 459, the plate 463 is rocked in a clockwise direction so that a shoulder 467 is placed in the path of 75

the cross bar of a control ball 468 that is fixed on shaft 469. Such cooperation of plate 463 and ball 468 will result in the shifting of the plate to the right, Fig. 14, which action is permitted by 5 the rocking of arm 465 on shaft 470. Springs 471, one for each arm, restore the arms 465 and the plates 463 to normal position and normally hold the arms 465 against stop rod 472. The front end of the cross bar on bail 468 cooperates 10 with a surface 463' in the shape of an arc about center 464 to aid in restoring plate 463.

When none of the plates 463 is rocked, the cross bar of ball 468 will swing beneath and to the right of the shoulder 467 on the plates. The 15 invariable oscillation of ball 468 upon each operation of the machine is accomplished with the devices shown in Fig. 1A. A cam groove 473 in the gear 68 cooperates with a roller on the end of an arm of a bell crank 474 to rock the crank 20 about its pivot 475 and shift a link 476 connected at one end to the other arm of the crank. The link 476 at its other end is connected to an arm 477 fast on the shaft 469. It is apparent that by the connections discussed, the movement of crank 25 474 by cam 473 will be imparted to shaft 469, thereby causing oscillation of ball 468.

Movement of any of the plates 463, Fig. 14, to the right will push a common rod 477' to the right. This rod is mounted in arms 478' attached to a shaft 479' pivoted in the side frames. Outside the left side frame is another arm 478' to which is pivoted a link 480' which extends to the right in cooperation with certain control elements yet to be described.

35 Before discussing the effect of the movement of any of the plates 463 to the right, Fig. 14, it is deemed advisable at this point to discuss the range control lever and connected devices.

The control lever 440 is pivoted on a stud 478 40 which projects from the outside of the left side frame 51. At its upper end, the lever is provided with a knob 479 which may be grasped by the operator in moving the lever into one of its five positions. The top of the lever moves along a 45 slot in a plate 480 that is fastened to the case 53. The slot has five notches in which a tab on the lever may be placed to locate and hold the lever in the position to which it is set. The names of these positions and their placement on the plate 50 480 is shown in Fig. 14.

Pivoted on the lower arm of the control lever 440, at 481, is one end of a link 482, the other end of which is connected to an arm on a cam plate 483 that is pivoted on a stud 484 in the 55 left side frame. By means on this connection, the movement of the lever is transmitted to the cam plate. In the position shown, Fig. 14, a hooked end 485 on the cam plate encircles a roller 486 mounted on an arm 487 that is fastened outside 60 the left side frame to a shaft 488. This shaft extends through the machine and has fastened to it, outside the right side frame, a control plate 489 which has cut in its end a cam slot 490 cooperating with a roller 491 on a bell crank 492. 65 This bell crank is pivoted on a stud 493 in the frame 50 and is connected by a spring 494 to another bell crank 495 also pivoted on stud 493 and carrying the broad toothed pinion 380 already mentioned. When bell crank 492 is rocked 70 clockwise by plate 489, bell crank 495 will be urged by spring 494 to also rock and disengage pinion 380, thus preventing printing. The movement of bell crank 495 is prevented, until the proper time, by an abutment 496 on the bell 75 crank which is obstructed by a stud 497 on a

lever 498 connected to the control operating link 476 already discussed. When the proper time is reached for the control function, which is when link 476 is operated, stud 497 will assume the dotted position, in Fig. 14, allowing bell crank 495 5 to rock clockwise and perform the various control functions to be described. Pivoted on the end of the vertical arm on bell crank 495 is a link 499 which forms an operating connection to the controlled devices.

A stud 500 on the side of the link 480', previously described, contacts the side of arm 482 so that when bail 478' is rocked this movement may be transmitted to plate 489. A slot 501 in link 480' surrounds stud 486 and guides the 15 link without interfering with movement of arm 481.

From the above broad outline of the control devices it is apparent that control plate 489 is rocked by single or combined action upon it by 20 two trains of connections; the one train consisting of fingers 423, plates 441, bail 449, plates 463, etc.; the other train comprising control lever 440 and cam plate 483. The various effects of the positioning of the control lever are 25 described in the next portion of this specification, then the effects of the raising and lowering of fingers 423 is taken up, and then the combined effect is discussed. The object of the control devices is to rock the bell crank 495 in a clockwise direction at the proper time so as to alter 30 certain functions of the machine.

When the lever 440 is in the "print" position, the hook 485 on plate 483 engages the roller 486 and holds the plate 489 with the upper end of the 35 cam slot 490 engaging the roller 491 and holding bell crank 492 in normal position. In this position of bell crank 492, a tab 502 on it holds the other bell crank 495 so that the pinion 380 remains in mesh with gears 377 and 379. Thus it 40 is apparent that a printing operation will be effected and the controls will not alter the normal functioning of the machine when the lever 440 is in "print" position.

In the next "below index" position of the lever 440, the plate 483 will be rocked so that the pin 486 will have relative position to the plate as shown by dotted pin 486', Fig. 14. Arm 487 is not rocked by this movement of lever 440, but the pin 486 is now clear of hook 485 so that 50 arm 487 may be rocked if bail 478' is actuated. The plate 489 and arm 487 are held rocked clockwise with the roller 486 against the cam faces on plate 483, by a spring 490' between plate 489 and the main side frame.

It may be noted here that any rocking of arm 487 and connected control plate 489 in a counter-clockwise direction, will shift the roller 491 and bell crank 492 by means of the cam faces in the cam slot 490. If plate 489 is rocked upward 60 one step, the cam face 503 in slot 490 will rock bell crank 492 in a clockwise direction. Two steps of upward rocking movement of plate 489 will bring the cam face 504 in cooperation with roller 491 and position bell crank 492 in normal 65 position, Fig. 14. Another step of movement of plate 489 brings the lower end of cam slot 490 into cooperation with roller 491, and again bell crank 492 is rocked clockwise into its controlling position.

Considering again lever 440, it is noted that when the same is put into the "exact index" position, a cam face 505 on plate 483 will rock arm 487, and pin 486 will assume the relative position 486'' to the cam plate. In this position 75

of arm 487, the cam face 503 is placed into co-operation with roller 491, and bell crank 492 is rocked clockwise with spring 494 urging bell crank 495 to assume its controlling and no print position. At this time, if plate 489 is not rocked another step upward by bail 478', a no print and controlling operation will occur.

In the next "above index" position of lever 440, the pin 486 will have a relative position 10 486" to the plate 483. In this position of cam plate 483, the arm 487 and control plate 489 will be rocked one step with roller 491 engaged by cam face 503 as was the case in "exact index" position. In the "above index" position, however, 15 a spacing finger 506 on a slide 507 is placed between stud 500 and arm 487 so that any movement of bail 478' will be transmitted immediately to arm 487, instead of allowing lost motion between stud 500 and arm 487 as is the case 20 when under "exact index" control at which time the pin 500 had to travel idly for one step of movement before contacting with the side of arm 487. From the above it is clear that bail 478' will have to rock two steps in "exact index" 25 control to produce the same effect that is produced by one step of movement of the same in "above index" control. The slide 507 carrying the spacing finger 506 is held on the cam plate 483 by pin and slot connections.

30 The "no print" position of lever 440 is the extreme rearward position of the lever. When the lever is put in this position, cam plate 483 is rocked so that a cam 503 engages the roller 486 and rocks arm 487 until the stud 486 is encircled by a hook 509 on the lower end of the cam plate. When arm 487 is in this position, the plate 489 is placed with the lower end of slot 490 engaging roller 491, thus rocking bell crank 492 and holding it in a position urging bell crank 495 into no-printing and controlling position.

40 Turning back to the connections to the bail 478' that cause it to rock either one or two steps in a counter-clockwise direction about shaft 479, it is noted that in order that bail 478' may be rocked, projection 448 of one of the plates 441 must be above the bail 449 so that link 459 may depress plate 469 into engagement with bail 468. The various conditions under which projection 448 will be positioned to allow bail 449 to engage it will now be discussed. An example will be taken of every case that may occur when knobs 420 are set to form a number, name, or date, and the actuators move to position the type bars to print a number, name, or date. It is noted the actuators may be moved under control of a punched card or under control of a totalizer wheel. So that control of the various functions of the machine may be had even without use of the punched card controlled devices.

50 Turning now to the discussion of the various conditions that exist in the machine when comparing the data set up by the operator with the data presented by movement of the actuators. 55 Taking a number, 78,365, for example, as the controlling factor, this number may be set up on the control plate by arranging the numerical knobs 420 along the slots until they are positioned to form the number 78,365. In the normal position of the actuators, all the numerical fingers 423 will now be held up on the upper level 433 on the numerical actuators, and the projections 448 on plates 441 will appear to the left of the cross bar of bail 449. Upon movement of the actuators, 70 75 if the highest order actuator, the tens of

thousands one, moves less than seven steps, the related finger 423 will remain on level 433 and plate 441 will be held to the left with its offset tab 445 holding all the lower order plates to the left, regardless of the extent of movement of the actuators related to the lower order plates. For instance, the number moved to by the actuators may be 69,999, whereupon all plates 441 except the higher order plate are urged by springs 444 to swing to the right but they cannot do so because they are held by the higher order plate. Thus, it is clear that if the number presented by movement of the actuators is less than the number set up by the control knobs, the plates 441 will not be lifted by bail 449 and bail 478' will not be rocked to the right by its associated parts. The same condition would exist if the letters MEN were set up to control, and the name actuators moved to LYX; or if the date June 15, 1920 were set up to control, and the date actuators moved to Dec. 31, 1919.

Another condition would present itself if, upon movement of the actuators, the highest order actuator would move beyond 7, to 8 or 9. The related highest order finger would then rest down 25 upon level 434, and projection 448 would be placed directly above the cross bar of bail 449 ready to be operated. The highest order plate 441 and its projection 448 will maintain this operative position regardless of the movement or lack of movement of the lower order actuators and plates 441. If the lower order actuators are moved an extent coinciding with the set up, say the number presented by the actuators is 98,365, the related fingers will fall into notches 435 and plates 441 30 will tend to swing to the extreme right, but they will be obstructed by the tab 445 of the highest order plate which is held in operative position. Upon the rocking of bail 449, the plate 441 will be lifted and through the connections already discussed, bail 478' will be swung slightly to the right. From the above it may be noted that when the number presented by the movement of the actuators is larger than the number set up by the control knobs, at least one plate 441 will be lifted 45 by bail 449, and bail 478' will be rocked. Conditions similar to these would prevail if the letters MEN were set up to control, and the name actuators moved to NEN; or if the date June 15, 1920 were set up to control, and the date actuators 50 moved to June 15, 1921.

Another condition would prevail if the actuators moved to represent exactly the amount set up, namely 78,365. Then, all the fingers 423 would fall into notches 435, and all plates 441 55 would swing together to the right, placing projections 448 to the right of the cross bar on bail 449 and out of its path. The bail 478' would not be moved under such conditions.

A still different condition would exist if one or a 60 few of the higher order actuators moved to the same digit or digits that were set up by the control knobs, say a number such as 78,432 were presented by the actuators. The two higher order fingers 423 would fall into notches 435 and related 65 plates 441 would swing to the extreme right. The hundreds order plate 441 and finger 423 would then become in effect the highest order, and if the hundreds actuator had moved to 4 the related plate 441 would be positioned above bail 449 for 70 actuation. However, if a number less than 3 had been presented by the hundreds actuator, the related hundreds plate would remain to the left and hold all the lower order plates in inoperative position. Thus, it is clear that not only by com- 75

paring the magnitude of the highest order of the data set up is control exerted, but in these devices every denomination of a number, or letter of a name is capable of determining whether the control devices should function or not, depending upon the magnitudes of the data presented and the data set up. Analogous cases would be presented if the aforementioned name or date were set up and MEX or Aug. 15, 1920 were presented by the related actuators.

When the control lever 440 is moved into "exact index" position, devices that change the relations between the devices for moving bail 478' are put into operation. This is done to secure a control for an exact comparison of data set up with data presented are put into operation. The bail 478' is adapted to be rocked a greater extent under this type of control.

An arm 510 on lever 440 is provided with a roller 511 which, when the lever is in "exact index" position, cams an arm 512' (Fig. 14) fastened to a shaft 513 outside the left side frame. Inside the main frames, the shaft 513 has mounted thereon a pair of arms 512 for each group of related fingers 423 and set up devices. A spring normally urges this assemblage counter-clockwise slightly to the left when not cammed to the right by roller 511. Slidably mounted on each pair of arms 512 is a coupling bail 514. Each of these bails has two depending slotted arms that guide them for vertical movement on studs in the arms 512. Since the arms 512 and bails 514 are in alignment on shaft 513, only one set is seen in Fig. 14. The cross bar of one of the bails is shown in section in Fig. 14. Pivoted to each of the links 429 and depending therefrom is a bar 515 which is guided in its vertical movement by a slotted plate surrounding its lower end. The bars 515 each have a horizontal notch 516 into which the cross bar of a coupling bail 514 can fit. Normally the bails 514 stand clear of the notches 516 and do not interfere with vertical movement of bars 515. However, when lever 440 is put in "exact index" position the bails 514 are inserted into notches 516 so that each bail will couple together the bars 515 of a related group of control devices, thereby causing all the fingers 423 of a group to move as a unit and to stand on level 433, or level 434, or to fall into notch 435 in the actuator as a unit. The fingers 423 do not necessarily have to remain in the same plane as shown in Fig. 14 but they can be set to any number, name, or date, and still they will be coupled as a unit and will only move down into notches 435 as a unit when the actuators are moved to extents that form data corresponding to those set up by the control knobs.

The arm 512 inside the left side frame has an extension to which is connected the right hand end of a horizontal arm on an L-shaped member 517. The mid-section of member 517 surrounds the shaft 461 previously mentioned, so that when the arms 512 are cammed to the right, shaft 461 will slide along horizontal slots in the side frames, thus swinging all the links 459 to the right until the pins 462 in the lower ends assume the dotted line position shown in Fig. 14. With the links 459 so positioned, if one of them is lifted it will tilt the plate 463 through a wider angle of movement than the movement received when tilted by links 459 in the normal position shown in Fig. 14. When so tilted, plate 463 will present a shoulder 518 to the bail 468. This shoulder 518 is a step closer to the cross bar of bail 468 than the shoul-

der 467, so that when plate 463 is moved to the right during "Exact index" control, bail 478' will be rocked twice the amount that it is rocked under the "Above" or "Below" index control.

The member 511 has a vertical arm that cooperates with bail 449. When the member 511 is moved to the right by the camming of plate 512, the upper end of this vertical arm will strike the bail 449 and carry it to the right so that the cross bar of the bail will be two steps to the right of the projections 448. In order for the projections 448 to be placed in a position so that plates 441 will be lifted by bail 449, the fingers 423 will have to fall into notches 435 allowing plates 441 and their projections to swing into the extreme right hand position.

From the above description it is clear that during "Exact index" control, the fingers 423 of a related group are coupled together, and the bail 449 is shifted so that only when the fingers 423 drop into the exact notch 435 will the plates 441 be lifted, and if any plates 441 are lifted, they will condition plates 463 so that bail 478' will receive twice its usual amount of movement.

A device for governing the amount of swinging movement of plates 463 is shown. This device is not necessarily provided for the correct functioning of the control mechanism as it may be dispensed with and still the control devices would be fully operative. A link 520 is connected to the bottom end of lever 440 and to the top end of an arm (not shown) on shaft 521 outside the left side frame. A pair of arms 522 are fastened to the shaft 521 inside the side frames, and they support a cross rod 523 that underlies all the plates 463. The lower edges of plates 463 are notched to limit the plates rocking movement by abutting the rod 523. In the "Print" position of lever 440, the rod 523 cooperates with a shoulder 524 on plates 463, holding them all up out of cooperation with bail 468. In the "Below index" and "Above index" positions of lever 440, the rod 523 underlies shoulders 525 and 526 respectively, and limits the downward movement to one step when shoulder 518 is in operative relation with bail 468. In the "Exact index" position of lever 440, the rod 523 is placed beneath a deep notch 527 in the plates 463, so that the plates may swing until shoulder 518 is presented to the bail 468. The shoulders 525, 526, and notch 527 are long enough to allow the plates 463 to have a sliding movement to the right as they are actuated by the bail 468.

When bail 478' is actuated it does not necessarily mean that control is to be effected, for roller 491 may be moved into either cam portion 503 or 504. It is only through the combined effect of the range control set by lever 440, and the comparison made by fingers 423 between the data presented by the actuators and the data set up, that control is effected.

At this point in the specification the combined effect of the two trains of controlling mechanism, namely, the devices under control of fingers 423 and devices under control of lever 440, may be considered, and the positioning of the bell crank 495 under such dual control is discussed.

Considering first the conditions prevailing when lever 440 is in the "PRINT" position, it is noted that the rod 523 on the lever 522 holds all the plates 463 out of cooperative relation with bail 468, thus preventing movement of arm 487 by the bail 478' and its connections. It is contemplated that an interlock may be provided between lever 440 and knobs 420 so that when the lever is in

"Print" or "No print" position the knobs are held in the position shown in Fig. 14. It is also noted that in this position of lever 440, the hook 485 on cam plate 483 holds the roller 486 so that both bell cranks 492 and 495 are held in normal position and no control will be exercised to change any of the functions of the machine.

When the lever 440 is in "Below index" position, and the control knobs are positioned to form a controlling name or number, the following conditions are obtained. The roller 486 and bell cranks 492 and 495 will remain in their normal position when the lever 440 is moved to "Below index" position. At this time the roller 486 assumes the position 486' with relation to the shifted cam plate 483, but pin 500 remains in contact with arm 487. However, lever 522 is swung so that the rod 523 is placed below a cut out portion 525 in plates 463, thus allowing them to drop one step if the movement of the actuators presents data greater in magnitude than the data set up by knobs 420. If the actuators are so moved and any one of plates 463 are lowered, the bail 478' will be swung slightly to the right, and by means of the cooperation between pin 500 and arm 487, controlling plate 489 will be rocked so that roller 491 is cammed into portion 503 of cam slot 490, thus putting bell crank 492 into a position wherein spring 494 urges bell crank 495 into controlling position, where it will be allowed to rock at the proper time when stud 497 is withdrawn from beneath shoulder 496 on bell crank 495. From the above it is clear that whenever the lever 440 is in "Below index" position, and the data presented by the actuators are of a greater magnitude than the data set up, the control devices will be actuated to change many of the functions of the machine. The machine will function in the normal way only if the data presented are below, in the scale, the data set up. Because the devices when so positioned provide such a comparison, this kind or range of control is named "Below index". If the operator of the machine wishes it to perform in the normal fashion, i. e., printing, sorting, accumulating, etc., only when the data submitted are "below" that arbitrary name, number, or date which he has set up, he chooses this range of control.

In the "Exact index" position of lever 440, the roller 486 is cammed to the right, and the roller 491 stands in cam portion 503 with the bell crank 492 urging bell crank 495 into controlling position. The rod 523 on lever 522 is positioned so that it is below the notch 527 in plates 463 so that the plates may descend two steps if the movement of the actuators presents data exactly the same as that data which are set up by the control knobs. If the actuators are so moved, and a plate 463 is lowered, the bail 468 will swing the plate and bail 478' two steps to the right. When bail 478' is so moved, the pin 500 in link 480' will move towards arm 487, one step of such movement will be idle and used to place the pin in contact with the arm, the next step of movement will rock the arm 487 and connected plate 489 so that the roller 491 will be forced into cam notch 504 in cam slot 490 and the bell crank 492 will resume its normal position. From the above description it is apparent that whenever the control lever is in "Exact index" position, and the data presented by the actuators are different from the data set up, the control devices will be actuated to change many of the functions of the machine. The machine will function in the usual way only if the data presented are exactly the

same as the data set up. Therefore, this type of control is named "Exact index" control. Thus, it is clear that the operator of the machine may set the control devices so that the machine will print, accumulate, take a total, etc., only when a certain name, number or date is among the data presented to the machine by the movement of the actuators under control of a punched card or the totalizer wheels.

If lever 440 is put in "Above index" position, the cam plate 483 will rock control plate 489 so that the roller 491 will stand in notch 503 of the cam slot 490, thus urging bell crank 495 into controlling position. At the same time the projection 506 will be inserted between pin 500 and arm 487 so that all movement of the bail 478' is transmitted to the control plate 489. The rod 523 on lever 522 will move to a position beneath shoulder 526 on the plates 463 so that they may drop one step if the movement of the actuators presents data greater in magnitude than the data set up on the control plate 487. If the actuators are so moved, and any of plates 463 are lowered, the bail 478' will be later swung slightly to the right by bail 468; and by means of pin 500, projection 506, and arm 487, controlling plate 489 will be rocked so that the roller 491 is cammed into portion 504 of cam slot 490, thus positioning the bell crank 492, back into its normal position wherein it does not urge the bell crank 495 into controlling position. From the foregoing it is clear that whenever the lever 440 is in "Above index" position, and the data presented by the actuators is below, in the alphabetic, date, or numerical scales, the data set up, the control devices will be actuated to change many of the functions of the machine. The machine will function in the normal manner only if the data presented are above, in the scale, the data set up. Therefore, this kind of control is called "Above index" control. When the operator of the machine chooses such control, he will expect the machine to print, add, take totals, feed paper, etc., only when the data on the punched card or totalizer wheel are "above" that certain name, number, or date which he has set up by the control knobs.

The condition of the control devices, as positioned by the lever 440 in "Above index" position, would serve equally as well on "Between index" control, in connection with the devices shown in Figs. 15 and 15A and already described. The bell crank 495 would be urged into controlling position unless the data presented by the actuators were between the limits of the data set up by the pairs of knobs 420. Then an actuator would be positioned with respect to the two knobs as shown in Figs. 15 and 15A, and plate 441 would be positioned with projection 448 in place to be engaged by bail 449. Under the latter conditions, the bell crank 492 would be pushed back into normal position, also holding the bell crank 495 in that position. It is to be noted that during "Between index" control, if the data presented to the machine are not between the range of values in the alphabetic, date, or numerical scale, set up by knobs 420, the control devices will be actuated to change some of the functions of the machine in a manner similar to that described in connection with the other ranges of control.

In the extreme right hand position of lever 440, the "No print" position, roller 491 is held in the bottom of cam slot 490 so that spring 494 urges bell crank 495 into controlling position. As long

as lever 440 is held in this position, a controlling position will be assumed by bell crank 495 upon each operation of the machine. The paper feeding, printing, and sorting devices will then be disabled or controlled while the control over the accumulating and total taking functions is optional and under control of the key 530, Fig. 1B.

The connections from the controlling devices to the various other mechanisms in the machine, 10 to enable the said devices to change the functioning of the said mechanisms, will now be considered. It is noted hereinbefore that when the bell crank 492 is rocked slightly in a clockwise direction, the lug 502 is moved away from bell 15 crank 495, and spring 494 urges this controlling bell crank into its controlling position. At the proper time for the control devices to function, the link 476 is shifted, and stud 497 is moved from beneath shoulder 496 on the controlling bell 20 crank, and it swings in a clockwise direction into its controlling position.

It is noted hereinbefore that the printing function is disabled in the machine when the broad toothed pinion 380, mounted directly on the bell 25 crank 495, is disconnected from gears 377 and 379. The connections from the controlling bell crank 495 for preventing paper feeding are also pointed out. They comprise link 412, Fig. 1A, arm 411, and broad toothed pinion 410. The connections 30 for controlling other functions in the machine will now be taken up.

To the end of the vertical arm of the controlling bell crank 495, Fig. 1A, is pivotally held one 35 end of a link 499 that extends down and to the right (Fig. 1B) where its other end is attached to the arm 531 on the sorting shaft 115. When the bell crank 495 is moved into the controlling position, the connections above mentioned will swing the sorting blade 116 into the dotted position, 40 thereby diverting the card 19, associated with the item causing the control devices to function, into the bin 111. From the foregoing description it is clear that the cards containing items that are printed, accumulated, etc., in the 45 normal manner, will fall into bin 112; and all cards containing data that is not printed, not accumulated, etc., and causing the machine to function in an unusual manner, will be separated from the rest of the cards and will fall into 50 bin 111.

At about the center of link 499 (Fig. 1B) there is loosely connected one end of a lever 532 pivotally mounted on a fixed stud 533 in frame 50, and having pivotally connected to its other end 55 a link 534. This link serves to engage and disengage the totalizers under control of the control devices, thus changing the function of the totalizers from adding to non-adding, from total taking to sub-total taking, and vice versa. Oper- 60 positely cut in the end of the link 534, are two notches 535 and 536, each of which is adapted to cooperate with pins 537 and 538 respectively, that are placed on the opposite sides of the pivot of a lever 539. This lever 539 is pivotally mounted on a stud 540 in side frame 50, and has a pin 541 on the upper arm, in engagement with a slot that is cut in the slide 339 described hereinbefore. When the slide 339 is shifted to the right to disengage the totalizers from the actuators, 65 the pin 538 will be placed to the left of a vertical line through pivot 540, and pin 537 will be positioned to the right, as shown in Fig. 1B. In this position of the pins, the right edge of upper notch 535 is in line with the right side of pin 537, 70 and the left edge of the notch 536 is in line with

the left side of pin 538. When the slide 339 is shifted to the left to engage the totalizers with the actuators, the lever will oscillate and pin 538 will appear to the right of pivot 540 and pin 537 to the left. Now, the pins 537 and 538 are in line with the ends of notches 535 and 536 opposite to the ends with which they were aligned at the disengaging position of slide 339.

Normally the link 534 is held out of cooperative relationship with the pins 537 and 538 by a bell crank 542. This crank 542 is pivoted on a stud 543 in frame 50 and has a converging notch 544 in its lower arm which confines a pin 545 on the link. The end of the upper arm of the bell crank is loosely attached to the end of the accumulation control key 530, so that if this key is depressed and latched by notch 546 to the case 53, the bell crank 542 will be rocked into a clockwise position wherein the pin 545 is released from the confines of notch 544, and the link 534 20 may be lowered or raised into cooperation with lever 539.

During adding operation, if the key 530 is depressed, the spring 547 will lift link 534 so that pin 537 enters into notch 535. Then, upon operation of the machine, the totalizers will be put into engagement with the actuators by the shifting of slide 339 to the left by the ordinary engaging devices, and pin 537 will be placed in contact with the left edge of notch 535. Upon operation of the control devices, if bell crank 495 (Fig. 14) assumes the controlling position, link 534 will be moved to the right, pushing pin 537 and slide 339 before it, thus disengaging the totalizers and causing a no-add operation. The 35 control devices are timed so that the totalizers are disengaged before the actuators start moving.

The same controlling operations would be employed if the machine were performing a sub- 40 total taking operation with key 354 depressed, only at this time the result would be that the operation would be changed to a total taking operation. During a sub-total taking operation, the totalizer is engaged with the actuators early 45 in the operation of the machine, and the wheels of the totalizer are turned back to their zero positions before the control devices are permitted to be actuated. So that after half of the sub-total taking operation is over, if the control devices do not push slide 339 to the right and disengage the totalizer, it will remain in mesh with the actuators and have the totalizer wheels turned back to the number that was previously cleared out. However, if the control devices do 55 act to disengage the totalizer, the totalizer wheels will remain at zero. Thus, the control devices serve to change a sub-total taking function into a clearing total function.

When the total key 356 is depressed, the relation 60 between the control devices and the totalizer engaging devices is changed, i. e., providing the key 530 is also depressed to allow controlling. A spring 548 is attached to the end of the total key 356 and is attached in turn at its other end to a 65 spring clip 549 which has a slotted end that confines a pin in the end of link 534. The slot in the spring clip 549 normally allows the link to rise under the tension of spring 547, but when the total key is depressed, the top end of the slot in 70 the clip will engage the pin on link 534 and by means of the heavy spring 548, the link 534 will be lowered until the notch 536 in it engages the pin 538. During the first part of the total taking operation of the machine, the slide 339 will be 75

shifted to the left by the engaging mechanism, thus engaging the selected totalizer with the actuators. Then, as the actuators move, the totalizer wheels are turned back to zero. Thus far the 5 operation is just as it is in sub-total taking. However, at this point, the engaging devices shift slide 339 to the right to disengage the totalizer wheels, so as to leave them standing at zero as they should be after a clearing operation. When 10 the slide 339 is so shifted, the pin 538 comes into contact with the left side of notch 536, and if link 534 is shifted by the control devices, then slide 339 will again be shifted to the left, again engaging the totalizer with the actuators which turn 15 the wheels back to the number that was cleared out during the first part of the operation of the machine. From the foregoing it is clear that if the control devices are actuated during a total taking operation of the machine, the operation 20 will be changed to a sub-total taking operation.

It is believed well to describe in detail at this point the suppression of total printing under control of the number comparing mechanism. The example to be considered is the one mentioned in the introduction of this specification involving total printing from only those account 25 totalizers holding less than \$200. To secure such control the operator moves the three lower order knobs 420 (Fig. 14) to the positions 200, and the lever 440 is moved to the "Below index" control position. This serves to place the hundreds order slide 423 on the level 426 to the right of the notch 435 in the hundreds order actuator 241 or 187. Lever 440 pulls rod 523 under shoulder 525 adapting plate 463 to drop with shoulder 467 in the path of bail 468 when ready for a control operation. The lever also pulls link 482 to rock cam plate 483 so that stud 486 is disengaged from hook 485 and in position 486' relative to plate 483.

40 The operator also positions lever 321 (Fig. 13) to select any one of the sixteen totalizers to control the total operation. Since a notch such as notch 311 is then aligned with a lug 2' the related totalizer is conditioned to mesh its accumulator 45 pinions with the actuators when the engaging control slide 261 (Fig. 1B) is moved to the right under the related roller 262.

Then the operator presses the sub-total key, and the stem 354 thereon rocks arm 350 in a 50 counterclockwise direction to push down arm 355 in a clockwise direction. Arm 355 is secured to shaft 149 (Fig. 5) which carries a bail rod 160 connected to another bail rod 162, said rods serving to depress the stop members 141, 146, 148, and 55 155 out of the path of the combination racks 143, 147, 151 and 153 so that the rack portion 187 of the actuator geared thereto may be moved freely by the accumulator pinions 251 (Fig. 9) meshing with teeth 189 (Fig. 5).

60 Then the machine is operated and early in the operation pin 346 (Fig. 1B) strikes crank 344 (now lowered on arm 350) and rocks it counterclockwise, thus shifting slide 339 to the left, and through arms 338, 336, slide 261 is moved to the 65 right to mesh the pinions of the selected totalizer.

Bail 167 rocks to the left (Fig. 5) so that springs 181 are free to urge the rack portions 187 of the actuators to move to the right a distance dependent on the amount in the accumulator and the 70 distance of large tooth 267 (Fig. 9) from the total stop 269. If the amount in the accumulator is less than \$200, the hundreds actuator 241 (Fig. 14) will not move to the right far enough to disturb the slide 423 which rests on level 426, and no 75 control will be exercised and the total will be

printed in the ordinary way. If, however, the total amount is \$200 or more, the hundreds actuator moves to the right far enough to drop slide 423 down to level 434 or 435. This movement initiates a chain of connections for suppressing the total print. Pin 427 lowers link 429 and allows arm 430 to rock down so that the abutting interposer 441 may rock to the right to place extension 448 over operator 449. When 441 is lifted by operator 449, pin 458 is lifted and the link 459 carrying it also rocks plate 463 by means of pin 462. This places shoulder 467 in the path of oscillating bail 468 which shifts the plate 463 to the right, rocking arm 478 and moving link 480, which rocks plate 489 to shift roller 491 in slot recess 503. As crank 492 is thus rocked clockwise, tab 502 thereon moves down and spring 494 lowers the horizontal arm of crank 495 to disengage the broad pinion 380 from the two gears 317, 379 and disconnect the printer drive connections 20 to disable total printing.

At the same time that total printing is suppressed, sub-totaling may be changed to clearing total taking if the control key 530 (Fig. 1B) is depressed to make effective the connections including link 499 (Fig. 14), lever 532 (Fig. 1B) and link 534. Shoulder 535 on link 534 is effective to push pin 537 and slide 339 to the right and cam slide 261 to the left to disengage the totalizer pinions. This control is effected at the middle of the 30 cycle at which time the pinions are restored to the zero position wherein they remain when disengaged. Therefore, although the selected totalizer was conditioned for a sub-total printing operation, instead total printing is suppressed and the 35 sub-total operation is changed to a clearing total operation because the amount held in the totalizer is larger than \$200.

Timing of the operating mechanism

Although the operating mechanism of the machine is described above in connection with each of the sections of the machine, it is thought that it would be well at this point in the description to describe the different operations or functions 45 of the machine in the order that they occur during operation of the machine. At the same time a résumé of the use of the illustrative machine as a whole will be given.

Before operation of the machine, the first 50 thing to be considered is the setting of the keys, knobs and levers in the machine to secure the kind of control desired. If no control is desired, i. e., all the data submitted by the cards are to be printed, added, sorted, etc., in the normal manner, none of the keys 353, 354, 356, and 530 is depressed, the knobs 420 are left in the position shown in Fig. 24, and the lever 440 is left in the "Print" position, and the lever 321, Fig. 13, is not moved. However, if control is desired, 60 many variations may be had because of the flexibility of the control present in the machine. The different modes of control are described.

If it is desired that the amounts associated with certain data should not be added in the totalizers, a no-add key 353 may be depressed to disable the adding function of the machine.

To secure a sub-total taking operation of the machine, the key 354 is depressed and the lever 321 is adjusted to select the desired totalizer.

To secure a total taking operation, the key 356 is depressed and the lever 321 is adjusted. During either of the total taking operations, a blank card may be placed in the sensing mechanism as the usual total card presented between groups 75

of cards in the machine. In the event that a blank card is in the machine, all the actuators except the amount actuators and the special bar 331, Fig. 13, will be held in normal position, and will print a dash, or leave a blank space on the record media. Should there be no card in the sensing devices, all the actuators, save the amount and special, will move to the end, in which position they will also print a dash or a blank as they did in normal position.

When it is wished to compare the data on the cards about to be run through the machine, with a certain name, number, or date, the operator of the machine sets the knobs 420 and adjusts the lever 440 to the range of control desired. Subsequent operation of the machine will cause the changing of many functions of the machine as a result of this comparison of the control mechanism, as described hereinbefore. If no such comparison or control is desired, the knobs are all left in the position shown in Fig. 14, and the lever 440 is brought to the "Print" position.

The lever 440 being brought to the no-print position will cause a no-printing operation without the necessity of any of the knobs being adjusted.

The special control of the totalizers in adding or total taking is optional and is made operative only when control key 530 is depressed.

After setting all the keys and levers to secure the control desired, and placing the record cards in the machine, the regular operation of the machine may be started. The motor of the machine is energized by closing a switch and the clutch 35 is closed by a touch bar (not shown) which is touched for a single operation and held down for continuous operation.

The first thing that happens as the machine is operated is the feeding of the card down into the sensing mechanism, for timing see Fig. 25. During this time the transfer pawls are fully disengaged from the totalizer wheels to allow the totalizer to move into mesh with the actuators if a total is to be taken. If a total or sub-total 45 is being taken, the totalizer is next lowered into mesh with the actuators. The sensing pins move through the holes in the card at this time to actuate the jacquard devices and limit the movement of the actuators. Before the actuators are moved, the transfer pawls, which are now latched down, are allowed to go into engagement with the totalizer wheels so as to act as a zero stop for total taking. Next, the actuators are allowed to move under the tension of their 55 springs, so that if a totalizer is meshed, its wheel will be turned back to zero and the actuators will be positioned in accordance with the number previously standing on the totalizer. After this operation, the transfer pawls are disengaged 60 from the totalizer wheels, and the actuators are engaged by pawls that prevent any additional forward movement of them on totals. At this next point in the operation, the bail preparing the control devices is actuated. If a total is being taken, the totalizer is now disengaged; or if 65 an adding operation is in process, the totalizers are engaged. Next, the control devices effect the many changes of function in the machine as previously mentioned. After which the transfer parts are restored and the paper is fed. Printing next occurs, if permitted by the control devices, and at the same time the transfer pawls are positioned to receive any transfers that may occur during the subsequent adding operation of the 70 totalizer wheels. The actuators are next re-

stored and in moving back they operate the totalizer in adding or the second half of a sub-total taking operation, and during this time the paper is cut allowing a bill or statement to issue from the machine. Also at this time the sensing pins 5 are withdrawn from the card. Next, the cards are dropped into the sorter, and the transfer pawls are then allowed to fully engage the teeth on the totalizer wheels so that as they are disengaged, the pawls may turn them a unit if a 10 transfer is due. Also at this time the holding pawls are lifted out of the teeth on the actuators. Finally, the control devices are restored, after which the totalizers are disengaged from the actuators, and the card release is closed to receive another card in the sensing mechanism.

While one admirable form of the present invention disclosing the many novel and improved features has been disclosed herein, it is to be understood that numerous modifications may be made in the specific constructions illustrated and described without departing from the spirit or scope of the invention. Not only is it contemplated that changes may be made in the specific mechanisms provided for the accomplishment of 20 various functions but if desired parts may be omitted or rearranged to bring about variations in the results effected. It is not desired to be limited other than by the scope of the claims which follow.

What I claim is:

1. In a device controlled by perforated record cards, means for feeding said cards through the device, means for sensing the presence of the perforations, two pairs of racks, means for moving said racks, means under control of said sensing means for controlling the movement of said racks, a pinion for each pair of said racks in mesh with rack teeth on both racks and mounted on a slide for rotation and linear movement given by 35 said racks, a pinion for each pair of said slides in mesh with rack teeth on both slides and mounted on a sliding rack for rotation and linear movement given by said slides, an actuator, and means for transmitting the movement of said 40 sliding rack to said actuator.

2. In a machine controlled by a perforated card a portion of which is devoted to a plurality of holes in combination representing one characteristic of the data on the card, a sensing device 50 for each perforation, a plurality of racks, means for moving said racks, means under control of the sensing devices for controlling the movement of said racks, a pinion for each pair of said racks being in mesh with rack teeth on both racks 55 and mounted on a slide for rotation and linear movement, said linear movement of said slide being one-half the combined movement of both racks, another pinion in mesh with rack teeth on each pair of said slides and mounted on a 60 slide rack for rotation and linear movement, said linear movement of said slide rack being one-half the combined movement of both slides, and gearing for multiplying the movement of the slide rack four times and transmitting it to an element 65 of the machine.

3. In a machine of the class described, a plurality of totalizers, actuating racks for the totalizers, means for engaging the totalizers with the racks, a bar which is adapted to select any one 70 or different pairs of said totalizers for engagement with said racks, the selected pairs always including a particular one of said totalizers, a perforated record card, means under control of said card for automatically shifting said bar to 75

- an extent determined by the perforations on said card in order to select a pair of totalizers, and a manipulative device for shifting said bar so that any one of said totalizers is selected for engagement with said racks. 5
4. In a machine of the class described, a plurality of actuators, means for determining the extent of movement of the actuators, totalizers operated by certain of said actuators, totaling mechanism for performing a clearing total or sub-total operation upon any of said totalizers, and control devices which determine whether a clearing total or a sub-total operation will be performed, depending upon the magnitude of the data presented by the positioned actuators. 10
5. In a machine of the class described, totalizers, means for entering amounts, means under control of said entering means adapted to move differentially for actuating said totalizers in adding, means for engaging the totalizers with, and holding the totalizers disengaged from the actuating means so as to perform an adding or non-adding function, means for setting up control amounts, means cooperating with said actuating 20 means and said control means for comparing the amount represented by the extent of movement of the actuating means with the set up amounts, and devices controlled by said comparing means for changing the mode of operation 25 of said engaging means from one function to the other during operation of the machine when the compared amounts disagree. 30
6. In a device controlled by record cards with a few perforation index positions and a series 35 of perforations in combination relating to a single characteristic of data, means for feeding the cards through said device, one card at a time, means for sensing the perforations in said cards, an actuator having a different position for each 40 combination of the perforations in the series, a rack for each perforation position in the series and means under control of said sensing means for selectively releasing said racks for movement, means for moving said racks, each of said racks 45 having an extent of movement which is a factor in the movement given to said actuator, and means for transmitting the movement of the racks to said actuator. 50
7. In a device controlled by a perforated record card having a series of holes present singly or in combination relating to a single characteristic of data, a sensing device for each hole, a differentially movable actuator, a latch under control of each sensing device, a rack under control of 55 each latch and released thereby when a related hole is sensed, each of said racks having a different invariable extent of movement, and means for transmitting the movement of the racks to said actuator. 60
8. In a device controlled by a perforated record card with a few hole index positions and a series of holes present singly or in combination relating to a single characteristic of data, means for sensing the holes in said card, a differentially 65 movable actuator, a plurality of racks one for each hole position of said series, means for moving said racks, latches for stopping and releasing said racks under control of said sensing means, and gearing for transmitting the movement of the racks to said actuator. 70
9. In a device controlled by a perforated record card having holes present in combination relating to a single characteristic of data, separate sensing devices for each hole, an actuator having 75 a different position for each combination of holes, a plurality of members each adapted for a different invariable extent of movement, means for moving said members, means under control of each sensing device for releasing a member which is adapted to move an extent which is a factor of the total extent of movement of the actuator, and means for transmitting the movement of all of said members to said actuator. 5
10. In a machine controlled by a perforated card a portion of which is devoted to a plurality 10 of holes in combination representing one characteristic of the data on the card, a sensing device for each hole, a plurality of racks, means for moving the racks, means under control of the sensing devices for releasing said racks for 15 movement, a pinion for each pair of said racks in mesh with rack teeth on both racks and mounted on a slide for rotation and linear movement perpendicular to the axis of the pinion, another pinion in mesh with rack teeth on each 20 pair of said slides and mounted on a slide rack for rotation and linear movement perpendicular to the axis of the pinion, and gearing driven by said slide rack for transmitting its movement to an element of the machine. 25
11. In a machine of the class described, a plurality of totalizers, actuating racks for the totalizers, means tending to engage the totalizers with said racks, a bar for obstructing the engagement of the totalizers but provided with notches to allow the engagement of the totalizers with the racks, the notches being so placed that upon movement and positioning of the bar in one direction one particular totalizer will always be engaged and a different one of the other totalizers 30 will be engaged for each step of movement of said bar, upon movement of the bar in the other direction only one of the same notches will be in a position to allow only one totalizer to engage 35 said racks. 40
12. In a machine of the class described, a plurality of totalizers, a grand totalizer, means for actuating the totalizers, a notched bar for selecting the totalizers for engagement with said actuating means, automatic means for positioning 45 said bar differentially in one direction during item entering operations, manipulative means for positioning said bar differentially in another direction for total taking operations, the arrangement of the notches being such that when the 50 bar is moved by the automatic means, a broad notch always selects the grand totalizer, and differentially spaced notches select one of the plurality of totalizers, and when the bar is moved by the manipulative means, only the differentially 55 spaced notches are used to select but one of the totalizers in each position. 60
13. In an accounting machine, a plurality of actuators, means for determining the extent of movement of the actuators, means for moving 65 said actuators, devices for accumulating the amounts presented by the actuators, and control devices which determine whether accumulating will occur or not, depending upon the magnitude of the amount presented by said actuators. 65
14. In an accounting machine, a plurality of actuators, means for determining the extent of movement of said actuators, means for moving said actuators, devices for accumulating the amounts presented by the actuators, and control 70 devices for determining whether the amounts will be accumulated or not, depending whether the data presented is above or below a point in the numerical, alphabetical or chronological scale set in said control devices. 75

15. In an accounting machine, a plurality of actuators, means for determining the extent of movement of said actuators, means for moving said actuators, devices for accumulating the amounts presented by the actuators, and control devices for controlling accumulation according to whether the data presented by said actuators are between certain limits, in the scale of the data, set by said control devices.
- 10 16. In a machine of the class described, a plurality of actuators, means for positioning said actuators, means for determining the extent of movement of said actuators, devices for accumulating the amounts presented by the actuators, and control devices which determine, during the operation of the machine, whether the amounts will be accumulated or not, depending upon the magnitude of the data presented by said actuators in the alphabetic, numerical, or chronological scale.
- 15 17. In a machine of the class described, a plurality of actuators, means for determining the extent of movement of the actuators, totalizers operated by certain of said actuators, totaling mechanism for performing a clearing or sub-total operation upon any of said totalizers, and control devices which determine whether a clearing or a sub-total operation will be performed depending upon whether the movement of the actuators is greater or less than a predetermined movement required by said control devices.
- 20 18. In a machine of the class described, a plurality of actuators, means for determining the extent of movement of said actuators to provide data handled by the machine, totalizers operated by some of the actuators, totaling mechanism for performing a clearing or sub-total operation upon any of said totalizers, and control devices which determine whether a clearing total or sub-total operation will be performed depending upon whether the data presented by said positioned actuators are between certain limits in the numerical, alphabetic or chronological scale, said limits being set in said control devices.
- 25 19. In a machine of the class described, a plurality of actuators, means for determining the extent of movement of said actuators to provide data handled by the machine, totalizers operated by certain of said actuators, totaling mechanism for performing a clearing or sub-total operation upon any of said totalizers, and control devices which determine whether a clearing total or a sub-total operation will be performed depending upon whether the data presented by said positioned actuators are above, below, or exactly of the magnitude of a requirement set by said control devices.
- 30 20. In a machine of the class described, a plurality of totalizers, means for actuating the totalizers, a means for entering data into the machine, means under control of said entering means for determining the extent of movement of said actuating means, means for engaging and disengaging the totalizers with the actuators, so timed as to secure different functions such as total taking or sub-total taking, and means controlled by the extent of movement of the actuators for automatically changing the timing of totalizer engagement from operation for one function into operation for the other.
- 35 21. In a machine of the class described, a storage accumulator, actuators for said accumulator, means for moving the actuators under control of said accumulator, printing devices for recording the extent of movement of said actuators in representing data, manipulative control elements for setting up controlling data, and control devices for comparing the data set up with the data represented by said actuators and means under control of said control devices for disabling printing if the data represented by said actuators does not agree with the data set up with said control elements.
- 40 22. In a machine of the class described, a plurality of actuators, means for positioning said actuators differentially, a totalizer cooperating with said actuators for accumulating amounts presented by the actuators, manipulative control elements, two cooperating with each actuator and settable variably to form a pair of names, numbers, and/or dates, and control devices for comparing the data in the range of the set elements with the data presented by the actuators and means under control of said control devices for withholding said totalizer from cooperating with the actuators as a result of the comparison.
- 45 23. In a machine of the class described, accumulator wheels, actuators, means for determining the extents of movement of said actuators, means for moving said actuators to the determined extents, in the first part of a cycle and back to normal position again in the second part of the same cycle, means adapted to connect said wheels with certain of said actuators, control means for operating in the first part of the cycle to sense the magnitude of a data value represented by the extents of movement of the actuators, and means under control of said sensing means and effective or ineffective according to the magnitude of data for selectively operating said connecting means to connect said wheels for accumulation in the second part of the cycle.
- 50 24. In a machine controlled by a record card with a plurality of perforation positions, a sensing pin for each of a pair of perforation positions, means for moving the pins when perforations are sensed, a rack formed with a shoulder and stop face, a latch cooperating with said rack, a lever pivoted on said latch and formed with two arms of equal length each abutting a pin for movement thereby when a perforation is sensed, the arrangement being such that in normal position the latch holds the rack from movement when no perforations are sensed, the rack moves one step when the latch is lifted by the lever to operate with the shoulder as either pin moves after sensing a perforation, and the rack moves two steps to the stop face when the latch is lifted further to clear the shoulder when both pins move the lever after simultaneously sensing two perforations.
- 55 25. In a machine controlled by a record card with a plurality of perforation positions, a sensing pin for each of a pair of perforation positions, means for moving the pins when perforations are sensed, a pair of racks one of which is formed with a shoulder, a pair of latches, one for each rack, a lever pivoted on the latch cooperating with the rack with the shoulder, said lever having two arms each abutting a pin for movement thereby when a perforation is sensed, the other latch abutting against one of the pins, the arrangement being such that both racks are held stationary by the latches when no perforations are sensed, the rack with the shoulder is moved one step when one arm of the lever is actuated by the one pin to shift the latch a slight amount, both racks are freed for movement by movement of the other pin which actuates the other arm of the lever and stops the shouldered rack after one step of move- 75

- ment while the other rack moves free since it is released by the latch operated by the same pin which actuates the lever, and when both performances are sensed, both latches are shifted to the 5 furthest extent and both racks make a complete movement, an actuator, and differential gearing between said racks and said actuator for imparting a summation of the movements of the racks to said actuator.
- 10 26. In a mechanism controlled by a record card with a plurality of perforation positions, a sensing pin for each of a pair of perforation positions on the card, means for moving the pins when perforations are sensed, a rack formed with two 15 differentially spaced shoulders and a slot, a latch cooperating with said rack, a two armed lever pivoted on said latch with a short arm abutting one pin and a long arm abutting the other pin, the arrangement being such that the rack is held 20 from movement when no perforations are sensed, the rack moves one step when the latch is lifted to cooperate with one shoulder as a perforation is sensed by the pin cooperating with the long arm, the rack moves two steps when the latch is 25 lifted further to cooperate with the other shoulder as a perforation is sensed by the pin cooperating with the short arm, and the rack moves three steps to the end of the slot when the latch is moved clear of the rack by both pins sensing 30 perforations, an actuator, and gearing between said rack and said actuator for transmitting the movement of said rack to the actuator.
27. In a machine of the class described, a totalizer, actuators for said totalizer, means for entering data into the machine, means for moving said actuators, means under control of said entering means for controlling the movement of said actuators to store data in said totalizer, means under control of said totalizer for determining the extent of movement of said actuators, devices under control of said actuators for printing a total of the data in said totalizer, other devices for clearing said totalizer, means for setting up a control amount for comparison with the 45 total amount that is represented by the extent of movement of said actuators and control mechanism cooperating with said actuators and said amount setting means for selectively operating both of said devices and dependent for operation 50 upon the magnitude of the movement of said actuators under control of said totalizer.
28. In a machine of the class described, a totalizer, actuators for said totalizer, means for entering data into the machine, means under control of said entering means for operating said actuators to enter the data into said totalizer, means for moving the actuators under the control of said totalizer, devices for clearing said totalizer and printing a total of the data represented by said actuators when positioned under control of said totalizer, manipulative control elements for setting up controlling data, and control mechanism for comparing the data set up with the data represented by the positioned 60 actuators when taking a total and capable of disabling said devices if the data represented by the actuators does not agree with the data set up by said control elements.
29. In a machine of the class described, a plurality of totalizers, means for entering amounts to add in said totalizers and data for selecting said totalizers, a totalizer selection member, means under control of said data entering means for automatically adjusting said member to select 75 totalizers to cooperate with said amount entering

means for amount entering operations, total taking devices, means for manually adjusting said member to select a totalizer for operation by said devices, a totalizer designating element under control of said automatic means, another totalizer designating element under control of said manual means, and means cooperating with said elements to print the designations of the selected totalizers. 5

30. In a machine controlled by record cards 10 with a plurality of sets of value representing designations in one column, a plurality of sets of analyzing devices aligned and arranged in a stepped formation, one set for each set of designations, a plurality of actuators one for each set 15 of said devices and all aligned therewith and arranged in stepped formation to coincide with the arrangement of the devices, and translating devices, one for each actuator, aligned with the related set of analyzing devices and cooperating therewith to translate the combinational designation analyses into differential movement of the actuators. 20

31. In a machine including accumulating and printing devices controlled by record cards having upper and lower sets of value representing designations, an accumulator, a set of accumulating and printing control actuators controlled by one set of designations, another set of printing control actuators interspersed between said first mentioned set of actuators and controlled by the other set of designations, means for analyzing both sets of designations, means under control of said analyzing means for controlling the positioning of both sets of actuators, two sets 25 of type carrying members on said actuators, an impression receiving means, and two separate operating means for moving said sets of type members against the impression receiving means to record two separate lines of print one beneath 30 the other, one line of print relating to accumulated data. 40

32. In a machine controlled by a record card with upper and lower sets of perforations in the same columns on the card, an accumulator for 45 accumulating data represented by the upper set of perforations, means for analyzing both sets of perforations, devices controlled by said analyzing means for translating said perforation analysis into differential movement, actuators relating to 50 the upper sets of perforations controlled by related translating devices to adjust the accumulating devices, a set of printing devices controlled by said actuators for printing the accumulated data, another set of printing devices interspersed 55 between said first mentioned set of printing devices, other actuators relating to the lower sets of perforations, interspersed between the first mentioned actuators and controlled by related translating devices to adjust the other set of said 60 printing devices, an impression receiving means, and means for bringing the two sets of printing devices against the impression receiving means at different times to record two lines of print one directly beneath the other, one line representing 65 accumulated data. 70

33. In a machine controlled by a record card with three sets of perforations in the same column on the card, one set relating to values to be accumulated, and capable of printing on a record 70 sheet, means for analyzing the sets of perforations, an accumulating device, first and second printing devices, an actuator related to one of said sets of perforations for adjusting the first printing device, another actuator related to the sec- 75

5 ond set of perforations for adjusting the second of the two printing devices, a third printing device related to said accumulating device, a third actuator related to the third set of perforations and interspersed between the other two actuators for adjusting said accumulating device and said third printing device, means under control of said analyzing means for operating said actuators, a pair of impression receiving members, and means

for bringing the first and second printing devices against one of said impression receiving members at a different time from that at which the third printing device is brought against the other member to print in two fields on said record sheet, one field beneath the other, one of the fields relating to accumulated values.

JOHN W. ARMBRUSTER.
